AUTOMATIC TELEPHONE SYSTEMS

Fernand Pierre Gohorel, Antony, France, assignor to International Standard Electric Corporation, New York, N.Y., a corporation of Delaware

Application January 25, 1956, Serial No. 561,327

Claims priority, application France March 9, 1955

14 Claims. (Cl. 179—18)

This invention relates to improvements in automatic telephone systems and particularly in translator registers that receive the number dialed by the calling party, translate it and send the various selective combinations required for the routing of the call.

In order to route a call it is often necessary to translate the office code received, in the case of an outgoing call, in order to direct the outgoing selector of the calling exchange and the selectors in the various transit exchanges and, in the case of a local call, in order to direct the local selectors, which are not necessarily arranged on a decimal basis. Considering that translators are complex and expensive devices, there is interest in shortening their holding time and hence their number.

One of the features of the invention is to provide arrangements in the register for discriminating the office code corresponding to local calls and for determining in that case the selective combinations required for the routing of the call, without necessitating the intervention of a translator.

Generally, the routing of an outgoing call requires the translation of a definite number of digits of the number dialed by the calling subscriber (code characterizing the called exchange or network); the seizure of the translator by the register will therefore be effected only after said digits have been received, in order to prevent useless locking of the translator. In certain special cases it may be necessary, either for determining the route or for determining the tolls, to translate a certain number of supplementary digits making up said number.

Another feature of the invention is that, following the reception of a certain definite number of digits of the number dialed, the register is connected to a translator and sends it said digits, said translator then determining the selective combinations required for the routing of the call, arrangements being provided to allow the translator to send the register a special signal where one or more supplementary digits are required for determination of the tolls, this having the effect of causing the register to release said translator and to seize a translator again upon the reception of said supplementary digits.

Another feature of the invention is that, when the number of digits received at the translator can determine neither the route nor the tolls, the translator sends the register a signal that causes the latter to release the translator, a translator being seized again only when the register has received the supplementary digit or digits that allow determining the route and the tolls.

In the case of a call originating from an exchange located ahead and intended for the exchange under consideration, it may happen that said exchange will receive only that portion of the code that is required for local selections, the circuits routing such calls being generally called "partial number" circuits.

Another feature of the invention is that, upon reception of a call coming from a partial number circuit and intended for a subscriber served by the exchange under

2

consideration, a special signal is sent to said register by the equipment associated with said circuit, arrangements being provided in said register to switch out the unused memories and to ensure reception of the portion of the code at the appropriate memories, said register itself providing the control of the routing and ringing operations without requiring the intervention of a translator.

When a call passes in transit through the exchange under consideration, the entire number dialed by the calling party can be received, the translations required for the routing of the call from said exchange onward being made in this very same exchange. The circuits receiving such calls are known as "complete number circuits."

Another feature of the invention is that, when the register is connected to the incoming equipment associated with a complete number circuit, a special signal characterizing the nature of said circuit is sent by said equipment to the register, the reception of this signal by the register causing it to control, after a given number of digits have been registered, the seizure of a translator, which then determines the signals required for the routing of the call.

Subscribers connected to a national network are generally divided into a plurality of areas. Within each of these areas a numbering scheme is provided using a code characterizing the called exchange or network and a numerical portion intended to make the selection of the called subscriber within said exchange or said network. For calls between two subscribers of one and the same area, it suffices to dial this code and this numerical portion or, in other words, the "office" code. On the other hand, for a call between two different areas, a "toll access" code characterizing national calls is dialed first, then an "area" code, followed by the "office" code described above.

Another feature of the invention is that, when the register receives the "toll access" code, it releases the memories used for the reception of said code and, if need be, switches in supplementary memories, in order to be able to receive the complete code characterizing the called subscriber within the national network, said register then seizing the translator following the reception of a given number of digits by sending it a suitable signal intended to control the translations required for the routing of national calls, this allowing using the same translators as for regional calls.

Special service calls are generally effected by dialing codes having a limited number of digits and always starting with the same digit.

Another feature of the invention is to use, for the translation of a special service number, two routing relays, one of them translating the first digit, common to all the special services, the other translating the second digit, denoting the category of the calling subscriber, the two digits translated being thereupon sent to the register, whereupon the call can be routed in a direction determined by the category of the calling subscriber.

Another feature of the invention is that, when the number of an absentee subscriber is dialed, the register receives from said subscriber's equipment a suitable signal that makes it release the seized selection chain and seize a translator, said translator then sending the register the signals that will cause the calling subscriber to be connected to an operator.

Another feature of the invention is that, when an absentee subscriber makes a call, a category signal is sent from said subscriber's equipment to the register, the reception of this signal by said register controlling the seizure of a translator and the transfer of the absentee

calling subscriber to an operator regardless of the number dialed by said subscriber.

It may happen that traffic is heavy between two exchanges and that it is desirable in that case to provide arrangements that will allow shortening the time required to establish connections.

Another feature of the invention is that, when the register receives the first digit of a number corresponding to a given direction, it itself controls the routing of the call to the next exchange and is then connected to a translator following the reception of a given number of digits, the seizure of this translator allowing the register to be supplied tolls information on the connection being established, arrangements being provided to release the chain partially established in case the number dialed does not correspond to the direction thus chosen.

When additional digits are to be sent to the translator, in order to allow it to bring about determination of the tolls, special arrangements must be made in order to limit the number of translating relays to be provided, this number increasing rapidly with the number of digits to be translated.

Another feature of the invention is that, when the determination of the tolls requires the translation of an additional digit, a device for decoding said additional digit and the contacts of the routing relay that has already translated the preceding digits or of an auxiliary relay associated to determine said codes are used in combination.

Various other features of the invention will become apparent from the following description, given as a non-limitative example with reference to the accompanying drawing, in which:

Fig. 1 is a circuit diagram used to explain the general operation of the system;

Figs. 2 and 3 are a schematic of the devices for sending and receiving numerical pulses;

Figs. 4 to 7 are schematics of the devices provided for registering the number dialed and the combinations translated;

Figs. 8 and 9 are a schematic of a translator;

Fig. 10 shows how to associate Figs. 2 to 9.

The general operation of the system will now be described with reference to Fig. 1.

Throughout what follows, the term "connector" shall mean a set of members arranged at the end of a circuit or of a line and intended to effect the connection between the circuit or the line and a special equipment of an exchange.

In the description that follows there will be discussed in succession the case of a call involving a local connection and that of a call involving an area connection. Various special cases, particularly involving national calls and calls to special services, will then be examined.

It will be assumed that the automatic switchboard involved serves a certain number of subscribers divided up into groups. A group selecting means selects the group comprising the called subscriber, a line selecting means selecting the called subscriber from among all those comprised in the group involved.

The case of a local call will be discussed first. When a calling subscriber *Ab* (Fig. 1) removes his handset, he finds himself connected, in accordance with a known method, to a register connector *JE1* having access to at least one free register. This connector is thereupon connected to a register *EN* through a register finder *CE1*.

When the register is in a position to receive the dial pulses, it sends the dialing tone to subscriber *Ab*. When the subscriber hears this tone, he may start to dial the called subscriber's number.

In the case of local and area calls, the number is made up of two different portions:

(1) An "office" code, characterizing the subscriber's exchange or group;

(2) A numerical portion, characterizing the subscriber within the exchange or the group.

The pulses sent out by the calling subscriber's dial are received by a pulse counter comprising a certain number of relays and forming part of register *EN*. When the sending of the pulses corresponding to a given digit ends, a certain number of metering relays are energized and then send information in coded form to special registering relays that memorize the digit just dialed by the calling party. The pulse counter thereupon homes and is ready to receive the pulse train corresponding to the next digit.

The registering relays corresponding to the code have a certain number of contacts used in three decoding pyramids, each comprising one incoming wire and two outgoing wires.

One of the outgoing wires of one pyramid can be connected to the incoming wire of the next pyramid by means of a jumper. The translation of certain special codes is thus obtained and particularly of those corresponding to a local connection, the reception of such codes being characterized by the energization of a special relay. It follows from this that the register itself discriminates local calls from area calls following the reception of the number code.

25 The control of the operations involved in the selection of the called subscriber will be effected in two stages:

(1) Control of the group selection operations that will allow choosing the line selecting means to which the called subscriber is connected;

30 (2) Control of the line selection operation that will allow selecting the called subscriber within the line selecting means to which said subscriber is connected.

Considering that a local call is involved, determination of the tolls and of the number of digits to be sent out again is superfluous.

Arrangements are provided to allow direct control, from the registering relays, of the group selection operations and subsequently of the line selection operations without the need of switching in a translator.

40 As soon as it discriminates the local nature of the wanted connection and it is in possession of the elements required for controlling the group selection operations, the register is connected to a group selection receiver *R1* through a receiver connector *CR*.

45 The register sends that receiver in coded form the selective combinations required for controlling the group selection operations.

Receiver *R1* thereupon receives, through register *EN* and receiver connector *CR*, an identity signal coming from the group selecting means *SG* seized by the calling subscriber. Once it has received that signal, receiver *R1* is connected to one of the two markers *M1* or *M'1* serving group selecting means *SG*, through contacts *mc1* or *m'c1* of multi-contact relays individual to said receivers and to said markers.

55 The selective combinations required for controlling the group selection operations are thereupon sent in code form from receiver *R1* to marker *M1* for example.

Group selecting means *SG* then selects, under the control of marker *M1*, a free trunk *lg1* giving access to the line selecting means *SL* to which the called subscriber is connected and connects itself to that line. Marker *M1* immediately sends a suitable signal to register *EN* to indicate that the group selection has ended, 60 whereupon it releases. Upon receiving this signal, the register in turn releases receiver *R1*.

When the calling subscriber has dialed the full number of the called subscriber, the register is connected to a line selection receiver *R2* through receiver connector *CR*.

70 As regards the line selection, it will be noted that line selecting means *SL* serves only a specific subscriber group. Therefore, it is not necessary to send receiver *R2* a signal identifying said line selecting means *SL*.

Considering that it has received and registered the called subscriber's number, register EN knows the identity of the line selecting means SL to which the called subscriber is connected and consequently can send directly to line selection receiver R2 an identity signal characterizing said line selecting means.

Line selection receiver R2 is connected to one of the two markers M2, M'2 serving line selecting means SL over contacts m_{c2} or m'_{c2} . Receiver R2, which has received in coded form from register EN the selective combination required for selecting the line, then sends said combination to marker M2 for example.

The line selection is accomplished under the control of marker M2. When it has been effected, marker M2 sends the register a special signal, as in the case of the group selection, and then releases. Upon receiving that signal, register EN releases receiver R2 and receiver connector CR and then in turn releases itself.

Called subscriber Ab' is rung if he is free and, upon his answering, the connection is established through register connector JE1, group selecting means SG and line selecting means SL.

The case of an area connection requiring the use of translator T will now be described. After removing his handset, calling subscriber Ab is connected to a register EN through means identical with those previously described. When the calling subscriber has dialed the code of the called subscriber's number and that code has been registered in register EN, the latter discriminates the area nature of said connection.

The register thereupon is marked calling on the banks of translator connectors CT. As soon as a free translator T has been found, register EN is connected to it through translator connector CT.

The register then sends the translator, in coded form, the code of the called subscriber's number. This code is received at translation relays that through a suitable arrangement of their windings and of their contacts cause the energization of a special relay. This relay then sends the register in code form the information required for controlling the group selection operations, for determining the number of digits to be sent out over the outgoing circuit and for the tolls to be charged to the calling subscriber.

That translated information is received in the register at relays that memorize it. These relays thereupon control the group selection operations in a manner identical with the one previously described.

When these group selection operations have ended, the group selecting means is connected to a line $lg2$ associated with an outgoing connector JD giving access to the wanted direction.

Inasmuch as the wanted connection is to a distant exchange, there is no line selection operation. When outgoing connector JD receives the invitation-to-send signal from the distant exchange, the register sends the outgoing connector the pulse trains required for the selection at said distant exchange.

Control of the sending of pulse trains to the outgoing connector is provided by a group of scanning relays whose energizing windings are successively brought under the control of registering relays by means of a chain of directing relays that advance one step after each pulse train. The starting position of the chain of relays depends essentially on the number of digits to be sent to the distant exchange.

When the sending of the pulse trains corresponding to all or part of the called subscriber's number has ended, register sends toll pulses to the meter TX associated with the outgoing connector. The establishment of the connection is effected thereupon in accordance with a known method. The register releases.

It may happen that the routing of an area call requires the translation of more digits than contained in the

code of the call number. Such for example is the case of calls requiring the translation of a supplementary digit for determining the tolls or those requiring the translation of a supplementary digit for determining the route and the tolls.

In the first case, provision is made, following the translation of the digits of the call number's code, for the simultaneous energization of two route relays: a main route relay and an auxiliary toll relay. The main route relay sends the register all the information required for controlling the group selection operations and for determining the number of digits to be sent to the distant exchange. The auxiliary route relay is inoperative at the moment under consideration. In addition to the route information it sends the register, the above route relay sends the register a special signal telling it that the translator needs a supplementary digit for complete determination of the elements required for the routing of the call involved.

Arrangements are provided to prevent the starting of the group selection operations until the register has received all the information required for the routing of the call.

In the present case, the register that has just received the information concerning the route but not the information concerning the tolls on the wanted connection cannot therefore control the starting of the group selection operations. The register however memorizes the information it has just received. The translator releases.

When the register has received the next digit, it again calls in a translator and is connected to it. It sends it the tone corresponding to the information required for the routing of the call. A main route relay and an auxiliary route relay energize. These relays further are the same as those previously mentioned, but the translator with which they are associated need not however be the same as the one first seized by the register in the course of establishing the present connection. The main route relay again sends the register route information; however, this produces no effect, since the register has memorized said information, which it had already received when it was first connected to a translator. The auxiliary toll relay, however, thanks to the supplementary digit received by the translator, allows determination of the toll information sent to the register. The latter then controls the routing of the call in accordance with a method already described.

In the second case, that is, in the case requiring the translation of a supplementary digit for determining the route and the tolls, the reception by the translator of the code of the called subscriber's number does not involve the energization of a route relay but is characterized by the sending of a special signal to the register telling it that a supplementary digit is needed for determining the route and the tolls corresponding to the desired connection. The translator releases and, when the register receives the supplementary digit, it again brings in a translator and sends it the number's code and the supplementary digit. A route relay then energizes and sends the register in coded form the route and toll information needed for the routing of the call.

For certain area calls it may happen that the translator needs an additional supplementary digit for determining the route and toll information required for the routing of the call. In that case, following the reception of the first supplementary digit the translator sends the register a second signal. This signal is different from the one first sent the register when the translator called for a first supplementary digit. Owing to this, the register itself can provide discrimination of the number of supplementary digits required by the translator. The translator releases after sending the register this second information. When the register receives this

supplementary digit, it again brings in a translator and sends it the number's code plus two supplementary digits.

The translation operations then follow in accordance with a method already described.

If following the reception of the code of a call number the translator itself can determine that two supplementary digits are required for determining the information needed for the routing of the call, it so tells the register by sending it the special polarity just mentioned above. It follows from this that said register will bring a translator in again only after receiving a second supplementary digit.

It is possible to associate with area connections calls coming from a circuit intended for a subscriber of the exchange involved and calls coming from a circuit intended for a satellite of the exchange involved, used in this case as a connecting office.

Depending upon operating requirements, therefore, two modes of operation can be provided for the register.

When a call coming from a circuit is intended for a subscriber of the exchange involved, incoming connector JA (Fig. 1) is so told and characterizes this circumstance by applying a characteristic potential to a so-called discrimination wire. A register EN is connected to incoming connector JA in accordance with a known method through a register connector JE2 and a register finder CE2. Thanks to the special polarity applied to the above-mentioned discrimination wire, the register is told of the nature of the calling party and of the destination of the call. The same as for local calls, arrangements are provided to prevent the register from being connected to a translator, since in this case the register itself controls the group selection and line selection operations. The digits received in the case of such a connection are only those making up the numerical portion of the called subscriber's number. In order to register these digits at the proper registering relays, the registering relays for the digits making up the call number's code are eliminated. When the register has received all the digits of the numerical portion, it controls the group selection and line selection operations in accordance with a method identical with the one described in connection with local calls.

When a subscriber makes a call intended for a satellite of the connecting office involved, the register at the originating exchange sends the connecting office the numerical portion of said subscriber's call number plus a certain number of digits of that number's code. The register at the connecting office must therefore register the received digits at the proper registering relay sets and, because of this, arrangements are provided to allow eliminating the first registering relay sets, corresponding to the digits not sent by the register at the originating exchange. When the register is connected to the translator, it sends it a special signal telling it that the translation to be made concerns a call passing in transit through the exchange involved and that therefore only part of the digits making up the call number's code will be sent it. The translator receives these digits at the translating relay sets corresponding to the places that they would normally have had if the code had been sent in whole by the register at the originating exchange. The translator then translates the code digit or digits it has just received. If the translation of a supplementary digit is required, it releases and is immediately seized again by the register in accordance with a method already described.

It may happen that the exchange involved is used as a transit office for toll calls. In that case, the incoming circuit sends the register at said transit office the full number of the called subscriber. Incoming connector JA applies a special polarity to the above-mentioned discrimination wire, thus telling the register that a transit call is involved. The sequence of operations then develops as in the case of an area call. However, no toll pulses are

sent, since it is a question of a call passing in transit through the exchange under consideration.

The routing will now be described in the case of a so-called "national" call.

The number for a national call generally comprises three different portions:

(1) A first code, characterizing the area in which the called subscriber is located;

(2) A second code, characterizing the exchange to which the called subscriber is connected within said area;

(3) A numerical portion, characterizing the called subscriber within the exchange serving him.

Owing to the amount of information involved in a national call number, it follows that the latter comprises a larger number of digits than used for local or area calls.

When the called subscriber is at a great distance from the calling subscriber, the translation of the code characterizing the area is sufficient to allow the register to determine the route and the tolls. However, in the case of a national call between two subscribers located but a short distance from each other, the translation of the first, of the second and even of some digits of the numerical portion may become necessary for determining the information required for establishing the route and for determining the tolls on such a call.

Upon removing his handset, the calling subscriber dials a special number characterizing a national call. The reception of that number at the register is effected as already described. This code is immediately translated in the register thanks to the aforementioned contact pyramids. After translation of this code, the register is told that a national call is involved and that it must accordingly (1) release the registering relays that had been brought into play to provide for the reception of the above

number and (2) send the calling party a special tone to invite him to dial the called party's number. When the register has received the first code, that is, the one characterizing the area in which the called party is located, it calls in a translator and connects itself to it in accordance with a method already described. When said connection becomes operative, the register sends the translator the above-mentioned code and a signal characterizing the fact that the received digits form part of a national-call call number. These digits are translated by suitable relays generally different from those assigned to area calls. A route relay is energized, this allowing sending the register the information needed for the routing of the call. The routing method is identical with the one described with reference to an area call. It is well to explain that generally the number of digits making up a national-call call number is larger than the one making up an area- or local-call call number. Arrangements are provided to increase the capacity of the chain of registering relays in the case of a national call. This remark further applies equally to the chain of directing relays controlling the aforementioned scanning relays.

If the routing of the call requires the translation of supplementary digits, the translator so tells the register and releases. The call routing operations are thereupon accomplished in accordance with a method already described.

A few special cases will now be described involving absent subscribers, restricted-service subscribers, etc.

It has been pointed out hereinbefore that a route relay upon energizing sends the register the signals required for the routing of the call. The arrangement is such that a route relay can send the register not only said signals, in ordinary cases, but also different route signals used in case of rerouting, in the case of restricted-service subscribers, etc.

A route relay, of course, provides only one route at a time. In order to determine a specific route from a given route relay, the translator has been provided with a certain number of category relays controlled by the

register and whose contacts constitute a discrimination pyramid providing the control for the route relays. Stated otherwise, when a route relay energizes, it can control a plurality of different routes, the choosing of any one of these routes being under the control of the above-mentioned discrimination pyramid.

The category discrimination relays are controlled by the register, which itself receives the information required for this control through the above-mentioned discrimination wire.

By way of example it will be assumed that the called subscriber involved in a local call is an absent subscriber. After receiving that subscriber's number, the register controls the routing of the call in accordance with the same method as for the general case. Since an absent subscriber is involved, a special polarity is sent from that subscriber's connector (not shown in Fig. 1) to the register's discrimination wire. The register then calls in a translator and, when the connection to that translator becomes operative, the register controls in said translator the energization of a route relay and of a discrimination relay, thus allowing said route relay to send the register the information needed for the connection of the calling subscriber to an operator.

If the call must be rerouted, the call is first routed as in the general case up to the point where the group selection operations are controlled by one of the two markers M1 or M'1. If all the normal routes are busy, the seized marker sends the register a signal characterizing this condition. The register recalls the translator, again sends it the number's code, this obviously involving the energization of the same route relay, and controls a special discrimination relay characteristic of the rerouting requirement. Owing to the pulling up of the discrimination relay, the above-mentioned route relay will now send the register such signals as to allow the wanted connection to be established over an emergency route.

If a restricted-service calling subscriber dials the number of an area call to which he is not entitled, the register is so told by the sending of a special polarity over the discrimination wire. The register is connected to a translator and controls the discrimination relays assigned to restricted-service subscribers. When the translator receives the called subscriber number's code, a route relay energizes, this relay obviously being the same one that would have energized if a regular subscriber had dialed the same number mentioned above. Owing to the pulling up of the discrimination relay assigned to restricted-service subscribers, the route relay that has just energized controls the sending to the register of information that will subsequently allow connecting the calling subscriber to an operator, while in the ordinary case it would have controlled the sending to the register of information that would have allowed the call to be routed to the distant exchange and from there to the called subscriber.

This description of the general operation will be brought to an end with a discussion of calls to special services. Generally, the special services are reached by dialing numbers comprising a small number of digits, always beginning with the same digit. Upon the reception of such numbers, the register calls in a translator and connects itself to it as already described. When the connection becomes operative, the register sends the number to the translator. The reception of this number at the translator involves the energization of two route relays: a main route relay and an auxiliary route relay. The main route relay characterizes by its energization the fact that the wanted connection involves some special service. It follows that this single route relay in the translator sends the register only part of the route information required for the routing of the call, the remaining portion of this information being dependent on the second digit of the number dialed by the calling subscriber and on said subscriber's category. It is the auxiliary route relay that performs the discrimination of the calling

subscriber's category and the translation of the number's second digit. There are as many auxiliary route relays as there are different categories of calling subscribers.

The auxiliary route relay then sends the register the rest of the route information required for the routing of the call.

The method is identical where special services are rung by means of three-digit numbers. A second auxiliary route relay is provided, controlled by the first auxiliary route relay. This second auxiliary relay can effect the translation of the number's third digit and thereby provide for the sending of the rest of the route information to the register.

A detailed description of the operation of register EN 15 and of translator T will now be given with reference to Figs. 2 to 9.

In the descriptions that follow, the relay windings are referenced by a combination of letters comprising two capital letters followed by one or more small letters.

20 The first capital letter characterizes the equipment in which the relay is used. All relays forming part of one and the same equipment therefore bear a reference beginning with one and the same letter. For equipment and wiring reasons, the relays of each equipment are 25 divided into groups, all the relays in a group being fastened to one and the same bar. The second capital letter in the relay's reference characterizes the bar. All the relays of one and the same bar are therefore referenced by one and the same second capital letter. The small letters 30 following the two first capital letters in a relay's reference denote the contact assemblies associated with the particular relay involved. On one and the same bar, the contact assemblies of the various relays are referenced in alphabetical order. Thus it is that on bar A of equipment R the first two relays each have two contact assemblies and the following two each have one assembly, the references used being then as follows:

First relay—RAab
Second relay—RAcd
Third relay—RAe
Fourth relay—RAf

The referencing of the relay contacts is as follows: for a given contact assembly associated with a given relay, 45 the contact references are obtained by having the two first capital letters making up the first portion of the relay reference followed by the small letter characterizing the contact assembly involved and by a digit locating the contact in that assembly. Thus it is that contacts RAc2 and RAD3 are respectively the second contact of assembly c and the third contact of assembly d of relay RAcd.

In certain cases, for the purpose of simplification, similar circuits or members performing identical functions are shown as a single member or circuit of each kind.

55 In this particular case, only the first and the last member are referenced, the references being separated by a diagonal line. Thus it is that a relay whose winding is referenced EPa/e actually represents five relays referenced EPa, EPb . . . EPe. Likewise, a relay contact referenced TJa/j, 2/11 actually represents the second, third . . . eleventh contacts of relays TJa, Tjb . . . Tlj or a total of 100 contacts (10 relays, 10 contacts per relay).

In order to make the drawing clearer, some wires that 65 must provide electrical connections between members far from each other have been grouped into cables. These cables are referenced by capital letters. The wires in a cable are referenced by a small letter preceded by the capital letter denoting the cable. In this connection, to prevent passing too large a number of wires or cables from one equipment to another, some relay contacts are shown in equipments to which actually they do not belong. These contacts are enclosed in a dotted-line rectangle. Of course, these contacts are referenced in accordance 70 with the equipment whereof they actually form part.

Thus, contact EFb_3 , shown in equipment R and encircled by dotted lines, belongs to relay EFb of equipment E.

Electrical connections that can be modified in accordance with operating requirements are shown in dotted lines.

It will be assumed first that the various members that will be used in the course of the description that follows are free. Under these conditions, all the relays and magnets shown in Figs. 2 to 9 are unoperated.

The battery normally used for the general supply of the system has its negative pole represented by an arrow; its positive pole is connected directly to ground.

It will be assumed as a nonlimitative example that the automatic switchboard involved serves 10,000 subscribers. These subscribers are divided into 20 groups of 500, each group being selected by group selecting means SG (Fig. 1) of a group selecting set. In the case of a local call the called subscriber is then hunted for by a line selecting means.

As already stated, when the subscriber removes his handset he is connected by known means to a register connector JE_1 having access to a free register EN. The connection of the free register to the register connector is provided by a register finder. The register finder is represented in simplified form in Fig. 3 by rectangle CE. As soon as the register can be connected to the register finder, magnet CEc is energized by battery applied to wire Ak_1 by the register connector.

Connecting relay CEc prepares a holding circuit for itself over its front CEc_9 . The seizure of the register is effected by the grounding of wire Ab_1 in the line selecting means, the effect of this being to energize seizure relay RCb and release-control relay $RCgh$:

(1) Battery, upper winding of relay RCb , back RCf_1 , RA_1 , wire Bb_1 , cable B, wire Bb_1 , front CEc_2 , ground on wire Ab_1 ;

(2) Battery, left-hand winding of relay $RCgh$, back RA_4 , ground over the circuit described above.

Seizure relay RCb will control the starting of the operations involved in placing the register in condition for receiving the dial pulses. Through the closing of front contact RCb_1 a ground is applied to test wire A_1 : ground, front RCb_1 , wire B_1 , cable B, wire B_1 , front CEc_4 , test wire A_1 .

The general ground required for the holding of the various relays of register EN is applied to ground wire tg by the closing of front RCb_2 . Connection magnet CEc of register finder CE has its holding circuit completed by the closing of front RCb_3 : ground, magnet CEc , front CEc_9 , wire BK_1 over cable B, front RCb_3 , battery.

The closing of front RCb_4 completes the circuit of pulse-receiving relay $RAab$, which pulls up: battery, left-hand winding of relay $RAab$, left-hand coil of transformer $RCcd$, front RCb_4 , wire Ba_1 , cable B, wire Ba_1 , front CEc_1 , wire Aa_1 , calling subscriber's loop, wire Ab_1 grounded in the line selecting means.

The pulse-receiving relay is a sensitive relay having only one front contact RAa_1 controlling auxiliary relay RCa . Relay RCa "duplicates" relay $RAab$ and operates in synchronism with it.

The energization of repeating relay RCa entails the energization of relay $RAcd$ by the closing of front contact RCa_1 : ground, left-hand winding of relay $RAcd$, front RCa_1 , resistance RR_2 , battery.

The closing of front contact RCa_2 is inoperative at the instant under consideration.

Relay $RAcd$ will hold throughout the use period of the register, its function being to control the connection of the calling party's circuit throughout the use period of the register, as will subsequently be explained. Over its front RAc_1 it applies a ground to holding wire Db to prepare the holding of the code-sending relays. Front RAc_2 prepares the energizing circuit of relay RCi over

wire k_1 . The function of the circuit including this wire will be explained subsequently. Front RAc_3 prepares the holding circuit of relay $RAcd$. Front RAc_4 completes the holding circuit of relay RCb ; battery, upper winding of relay RCb , back RCf_1 , RA_4 , front RAc_4 , ground.

Over its front RAc_5 relay $RAcd$ completes the energizing circuit of relay $RDab$ (Fig. 3): battery, relay $RDab$, front RAc_5 , back REq_1 , holding wire Db , front RAo_1 , ground.

Make-break contact RAd_1 directs wire Bb_1 to the right-hand winding of transformer $RCcd$ and of relay $RAab$. This contact operates at the same instant as front RAc_4 . The result of this is that the energizing circuit of relay RCb is broken for a moment. However, this relay cannot fall back, because its lower winding is short-circuited, this imposing a certain delay on the release of this relay. The closing of front RAd_2 has no effect at the instant under consideration, because front RCb_2 is already closed. The same applies also to front RAd_3 , which will short-circuit front RCb_3 . Over its front RAd_4 relay $RAcd$ grounds test wire A_2 : test wire A_2 , front CEc_5 , wire B_2 , cable B, wire B_2 , front RAd_4 , back RCf_5 , EFc_2 , ground.

Make-break contact RAd_1 causes the looping of the subscriber's line to dialing relay $RAab$, while the ground applied to wire TBb_1 in the line selecting means is removed: battery, left-hand winding of relay $RAab$, left-hand winding of transformer $RCcd$, front RCb_4 , wire Ba_1 , cable B, wire Ba_1 , front CEc_1 , wire Aa_1 subscriber's loop not shown, wire Ab_1 , front CEc_2 , wire Bb_1 , cable B, wire Bb_1 , front RAd_1 , RCb_5 , right-hand winding of transformer $RCcd$, right-hand winding of relay $RAab$, ground. The middle winding of transformer $RCcd$ is supplied alternating current by tone generator RG_3 over the following circuit: ground, middle winding of transformer $RCcd$, back EH_3 , EH_1 , EH_4 , EId_5 , EE_3 , tone generator RG_3 , ground.

The closing of front RAd_1 causes the looping of the subscriber's line to dialing relay $RAab$, while the ground applied to wire TBb_1 in the line selecting means is removed: battery, left-hand winding of relay $RAab$, left-hand winding of transformer $RCcd$, front RCb_4 , wire Ba_1 , cable B, wire Ba_1 , front CEc_1 , wire Aa_1 subscriber's loop not shown, wire Ab_1 , front CEc_2 , wire Bb_1 , cable B, wire Bb_1 , front RAd_1 , RCb_5 , right-hand winding of transformer $RCcd$, right-hand winding of relay $RAab$, ground. The middle winding of transformer $RCcd$ is supplied alternating current by tone generator RG_3 over the following circuit: ground, middle winding of transformer $RCcd$, back EH_3 , EH_1 , EH_4 , EId_5 , EE_3 , tone generator RG_3 , ground.

The two secondary windings of transformer $RCcd$ having just been looped by the closing of front RAd_1 , an A.C. superimposed on the supply D.C. will flow in the subscriber's loop. The subscriber, then hearing that tone, is thus told that he has just been connected to a register and that the latter is ready to receive the numerical pulse trains corresponding to the wanted subscriber's number.

RC_{a1}, energizes: battery, resistance RR₂, relay RC_e, front RC_{a3}, back RC_{a1}, ground.

Relay RC_{a4}, short-circuited by the closing of back contact RC_{a1}, is slow in releasing, this allowing it to hold until the end of the pulse under consideration.

The passing to front position of make-break contact RC_{e1} has the effect of removing the short-circuit from the energizing winding of relay RC_k and of completing the energizing circuit of said relay, which then pulls up: battery, resistance RR₁, relay RC_k, front RC_{e1}, wire Da over cable D, back EH_{e2}, ground over wire tg.

The closing of front RC_{e2} completes the energizing circuit of relay EH_h (Fig. 4): battery, relay EH_h, back EI_{d2}, wire D_d over cable D, front RC_{e2}, ground on general holding wire tg.

The opening of back RC_{e3} prevents, owing to the subsequent closing of front RC_{k1} to RC_{k5}, the sending of a ground to the coding contact pyramid, connected between back RC_{e3}, and front RC_{k1} to RC_{k5}.

Through the closing of its front contacts RC_{k1} to RC_{k5}, relay RC_k prepares the connection of the coding contact pyramid to registering relays EO_a . . . EO_e. Through the closing of its contact RC_{k6} it completes the following holding circuit for itself: battery, resistance RR₁, relay RC_k, front contact RC_{k6}, wire Da over cable D, back EH_{e2}, ground on general holding wire tg. Further, the closing of this front contact controls the sending of the general ground to the receiving relays forming part of equipment NR. The circuit used for sending pulses to this latter equipment is prepared by the closing of front contact RC_{k7}.

Relay EH_h completes a holding circuit for itself by the closing of its front EH_{h2}: battery, relay EH_h, back EI_{d2}, front EH_{h2}, ground on general holding wire tg.

The opening of back contact EH_{h4} breaks the primary winding of transformer RC_{cd}, the effect of this operation being to eliminate the sending of dialing tone to the calling subscriber's loop. This break is made therefore as soon as the calling subscriber has released his dial after having dialed the first code digit.

Relay RA_{ab} and relay RC_a energize again at the end of the first pulse. Make-break contact RC_{a1} short-circuits relay RC_e and completes the energizing circuit of relay RC_{a4}. Relay RC_{a4}, which had its left-hand winding short-circuited for the duration of the pulse by back contact RC_{a1}, has not released. It is now relay RC_e that is short-circuited. Owing to the short-circuiting of relay RC_e, this relay does not release during the time interval separating the reception of two consecutive pulses. The closing of front contact RC_{a2} completes the circuit for sending pulses to meter NR: meter NR, wire NR_c, front contact RC_{k7}, RC_{a2}, ground over the circuit already described.

The reception and the coding of the received digits are effected in a meter NR represented in the drawing by a rectangle. This device has already been described in a patent application filed by R. L. M. Le Quean on December 19, 1955, Serial No. 554,023 and entitled "Improvements in Telephone Systems." This device comprises six metering relays, RA_e, RA_f, RA_g, RA_h, RA_i, RA_j, whose windings are not shown in the drawing. Depending upon the digit received, some of these relays can hold at the end of a pulse train over holding wire NR_b, connected to the general ground wire through front contact RC_{k6} as already pointed out. The sending of pulses to the meter is effected by beating-contact RC_{a2}. A certain number of metering relays are energized at the end of each pulse, the energization of these relays characterizing the serial number of the last pulse received or, what amounts to the same, the number of pulses received from the beginning of the pulse train involved. The following table gives the selective combinations of metering relays energized for received-pulse numbers comprised between 1 and 10. In this table the letter R denotes the metering

relays in unoperated position; the letter T denotes the metering relays in operated position.

5	Relays	RA _e	RA _f	RA _g	RA _h	RA _i	RA _j
1		T	T	T	R	R	R
2		R	R	T	T	R	R
3		T	T	R	T	T	R
4		R	R	R	R	T	R
5		T	T	T	R	T	R
6		R	R	T	T	T	R
7		T	T	R	T	T	T
8		R	R	R	R	R	T
9		T	T	T	R	R	T
10		R	R	T	T	R	T

15 To use this table a digit dialed is chosen, digit 6 for example; reading the line corresponding to that digit it will be seen then that relays RA_g, RA_h and RA_i are in operated position.

The metering relays have a certain number of contacts shown in Fig. 2 in equipment R. These contacts form a pyramid comprising one incoming wire capable of being grounded and five outgoing wires Ca, Cb, Cc, Cd and Ce. The combination of metering-relay contacts allows sending grounds over two of the 5 coding wires mentioned above, for each digit received by the meter. Thus is formed a 5-element code using two predetermined elements for each digit. As is known, this well-known code allows obtaining 10 different combinations corresponding to the 10 different digits that can be dialed by the subscriber.

20 The following table gives the code used within the framework of the present invention.

Digits	1	2	3	4	5	6	7	8	9	0
35 Wires.....	{Ca Ce	{Cb Ce	{Ca Cb	{Cc Ce	{Ca Cc	{Cb Cc	{Cc Cd	{Cd Ce	{Ca Cd	{Cb Cd

It can be seen from this table that when dialing digit 40 6, for example, a ground is applied to wires Cb and Cc.

The discussion will now be resumed of the reception of the called subscriber's number at the end of the first pulse corresponding to the first digit dialed. As previously pointed out, a ground is applied to wire NR_c owing to the closing of front contact RC_{a2}. That ground causes the energization of metering relays RA_e, RA_g. The energization of these relays has no effect at the instant under consideration, because the coding contact pyramid is not supplied, due to the opening of back contact RC_{e3}. Relays RA_{ab} and RC_a release at the beginning of the next pulse. A cycle identical with the one previously described recommences. Relays RA_{ab} and RC_a energize at the instant corresponding to the end of the ninth pulse. The closing of front contact RC_{a1} short-circuits relay RC_e, which will release with a certain delay. The closing of front contact RC_{a2} causes the sending of a ground over wire NR_c to meter NR, the effect of this being to energize metering relays RA_c, RA_f, RA_g, RA_j, as follows from a previously-described table.

55 At this moment the calling subscriber's dial has returned to normal and relay RC_e released, thus marking the end of the first pulse train.

50 The release of relay RC_e will cause the first digit of the called subscriber's number to be sent to the metering 60 relays in coded form.

Through the return to normal position of its make-break contact RC_{e1}, relay RC_e short-circuits the winding of relay RC_k, which will release with a certain delay. The opening of front contact RC_{e2} breaks the energizing 70 circuit of relay EH_h, which holds through its holding contact EH_{h2} over a circuit previously described. The closing of back contact RC_{e3} completes the grounding circuit of the coding wires Ca, Cd, corresponding to digit 9.

75 (1) Wire Ca, front contacts RC_{k1}, RA_{f4}, RA_{e1}, back

contacts RA₁, RC_{e3}, ground over a circuit already described:

(2) Wire Cd, front contacts RC_{k4}, RA_{j1}, then ground on wire tg over a circuit already described.

Coding wires Ca . . . Ce are connected to a metering relay set whose operation will now be explained.

As previously pointed out, seven-digit dialing is used, three digits for the code and the other four for the numerical portion. Since the code chosen for sending the digits received by the metering relays to the registering relays comprises five elements, it follows that the total number of registering relays to be provided is 35 (the 7 digits to be sent require 5 registering relays each). Fig. 4 shows only 7 registering relays, each of them actually corresponding to the five registering relays associated with the digit involved. The following table gives the references of these various relays:

Digits						
P	Q	R	M	O	D	U
EO _a	EP _a	EQ _a	ER _a	ES _a	ET _a	EU _a
EO _b	EP _b	EQ _b	ER _b	ES _b	ET _b	EU _b
EO _c	EP _c	EQ _c	ER _c	ES _c	ET _c	EU _c
EO _d	EP _d	EQ _d	ER _d	ES _d	ET _d	EU _d
EO _e	EP _e	EQ _e	ER _e	ES _e	ET _e	EU _e

It can be seen from this table that the registering relays corresponding to digit R, for example, are referenced EQ_a, EQ_b . . . EQ_e. The five relays shown in Fig. 4 as a single relay bear the reference EQ_{a/e}. A similar reasoning is applicable to the 30 relays for the other six digits.

The relays corresponding to one and the same digit are designated *a* to *e*, these references agreeing with those given to the coding wires Ca . . . Ce. The windings of the five registering relays for a given digit of the call number can be connected by circuits that will subsequently be described to the five coding wires mentioned above. Thus, upon the reception of digit R, for example, registering relays EQ_a . . . EQ_e will be connected to coding wires Ca . . . Ce.

These explanations will make it possible to continue the description of the registering of the digits dialed. The five registering relays EO_a . . . EO_e for the first digit (P) are connected to the five coding wires Ca . . . Ce through the five back contacts EI_{c1} . . . EI_{c5} shown in the figure as a single back contact EI_{c1/5}.

In the present case the calling subscriber has just dialed the first digit, the digit 9 in the example chosen, and coding wires Ca, Cd have just been grounded as previously explained. This grounding has the effect of energizing registering relays EO_a, EO_d over the following energizing circuits:

(1) Battery, relay EO_a, back EI_{c1}, ground on wire Ca over a circuit previously described;

(2) Battery, relay EO_d, back EI_{c4}, ground on wire Cd over a circuit previously described.

These relays prepare a holding circuit for themselves through the closing of their front contacts EO_{a1} and EO_{d1}. These contacts are shown as a single front contact referenced EO_{a1/d1} and representing the five front contacts EO_{a1} . . . EO_{d1} associated with metering relays EO_a . . . EO_e. All of these front contacts are connected to the general holding wire through the winding of relay EI_c and back contacts EE_{n6}. However, relay EI_c remains unoperated, due to the fact that the two ends of its energizing winding are grounded at the desired instant. The closing of front contacts EO_{a2} and EO_{d2} completes the energizing circuit of scanning relays RB_a and RB_d (Fig. 3). The energizing circuit of these relays, which perform no function in the case of a local call, will not be described. The closing of front contacts EO_{d5} and EO_{a6} prepares the energizing circuit of relay EF_f.

Relay RC_k, whose winding had been short-circuited by the closing of back contact RC_{e1}, releases in turn after a certain delay. The opening of front contacts RC_{k1} . . . RC_{k5} has the effect of breaking the connections existing between coding wires Ca . . . Ce and the windings of registering relays EO_a . . . EO_e. The two relays EO_a and EO_d that were energized hold over a circuit previously described, this having the effect of energizing relay EI_c, whose winding has just had its short-circuit removed due to the removal of the ground that was sent to the two registering relays EO_a and EO_d. The opening of front contacts RC_{k6} and RC_{k7} breaks the holding circuits of metering relays RA_e, RA_f, RA_g, RA_j, which release in turn.

Relay EI_c marks by its energization the end of the operations involved in registering the first digit of the called subscriber's number.

The passing into operating position of the five make-break contacts EI_{c1} . . . EI_{c5} directs the five coding wires Ca . . . Ce to the five registering relays EP_a . . . EP_c charged with registering the number's second digit.

20 The closing of front contact EI_{d1} prepares the energizing circuit of relay EF_f. The opening of back contact EI_{d2} breaks the energizing circuit of relay EH_h, which releases. The closing of front contact EI_{d3} prepares the energizing circuit of the relay RC_f that transfers the calling line to faulty operation. The opening of back contact EI_{d4} prevents further sending of ringing tone to the calling subscriber's circuit, when relay EH_h releases.

30 The release of relay EH_h has no effect at the moment involved.

The operations that have just been described recur identically for the registering of the next digit, the digit

35 6 in the example chosen. After the release of relay RC_k, marking the end of the registering of said second digit, relays EP_b, EP_c, EG_{f/g} are still energized.

At the end of the registering of the number's third digit, the digit 5 in the example chosen, relays EQ_a, EQ_c, EG_{f/g} energize.

40 At the instant under consideration the register has just received the code (965) for a local call. The energization of registering relays EO_a, EO_d, EP_b, EP_c, EQ_a, EQ_c will allow the register to detect the local nature of the wanted connection. This detection is provided by 45 relay EF_f, which energizes. To do so, the registering relays associated with each digit form through a suitable arrangement of their front contacts decoding pyramids having one incoming wire and ten outgoing wires (Fig. 6). When two registering relays for a given digit 50 energize, metallic continuity is established between the incoming wire and the outgoing wire corresponding to the value of the digit that has just been registered. When it is desired to provide discrimination for a special code made up of three digits, it suffices to jumper one of the 55 outgoing wires of the first decoding pyramid to the incoming wire of the second and so on. In the special case here described as an example, relay EF_f detects the calling subscriber's dialing of the selective combination 60 965. This relay indeed has its energizing circuit completed as follows: battery, relay EF_f, jumper m₃, front contacts EQ_{c4}, EQ_{a5}, EG_{j3}, back contact EE_m, jumper m₂, front contacts EP_{c5}, EP_{b5}, EG₃, back 65 EE_{m1}, jumper m₁, front contacts EO_{d5}, EO_{a6}, EI_{d1}, back contacts EE_{n5}, EC_{m2}, wire R_g, back EF_{c4}, ground on general holding wire tg.

60 The energization of relay EF_f tells the register that the connection that is going to be established is a local connection and that therefore the use of the translator is superfluous.

65 As previously pointed out, the exchange with which the register here under consideration has been assumed to be associated comprises 10,000 lines divided into 20 groups of 500, each group being served by a so-called line-selecting means. Group selection should allow rout-

ing a call in progress from the register connector to the line-selecting means to which the called subscriber is connected. It follows from this that for local calls alone the group-selecting means will have 20 outgoing groups. Moreover, as will subsequently be explained, a certain number of groups are provided for outgoing calls to distant exchanges. From this it follows that the numbering scheme used by the register to control the group selection, whether for a local or for a toll call, should comprise 2 digits, this allowing obtaining 100 different selective combinations. In order to save time in transmission operations, use is made of a coded numbering scheme identical with the one used to send the digits received from the metering relays RA_e . . . RA_j to the registering relays EO_{a/e} . . . EU_{a/e}.

To register the 2-digit selective combinations required for the group selection use is made of 10 registering relays divided into 2 groups of 5, each group corresponding to one of the digits making up said selective combinations. These relays, referenced EW_a . . . EW_e for the first group and EX_a . . . EX_e for the second, are shown as 2 relays only, referenced EW_{a/e} and EX_{a/e}. The energizing windings of relays EW_a . . . EW_e are connected to the coding wires referenced Ew_a . . . Ew_e. Likewise, relays EX_a . . . EX_e are connected to the coding wires referenced Ex_a . . . Ex_e. These wires are all grouped into cable E, terminating at translator T through translator connector CT.

Over these wires are sent from the translator polarities that energize for a special translation 2 relays EW and 2 relays EX, the energization of these relays thereupon allowing the group selection that subsequently allows connecting the register connector to the originating connector associated with the outgoing circuit that must route the call to the distant terminating exchange. As previously stated, the translator is not associated with the register in the case of a local call. In other words, the register itself must provide the translation of the received code to determine the elements required for the control of the group selection. Since that group selection is provided by the energization of 2 relays EW and of 2 relays EX and since these relays cannot be energized over the path previously described, the translator not being connected to the register, it follows that shunts have been provided on some of the wires Ew_a . . . Ew_e and Ex_a . . . Ex_e. These shunts terminate at coding contacts whose operation will be explained later on in this description. The above-mentioned special shunts will be termed "local coding wires" in what follows.

Knowing the first two digits of the call number's numerical portion is a condition at once necessary and sufficient in order to be able to determine the routing of the call from the register connector to the line-selecting means serving the called subscriber. As previously pointed out, the subscribers are associated in groups of 500 to form a line-selecting means. Consequently, a group of 1000 subscribers comprises 2 line-selecting means. Stated otherwise, in order to identify a particular line-selecting means, it suffices to know the 1000-subscriber group comprising the called subscriber and to determine whether said subscriber forms part of the first or the second 500-subscriber group making up the 1000-subscriber group in question.

The coding of the thousands digit is provided by relays EX_a . . . EX_e, which for a local call "duplicate" the thousands-digit registering relays ER_a . . . ER_e. The coding of the digit characterizing the 500-subscriber group comprising the called subscriber is provided by relays, EW_a, EW_b, EW_d. It will be noted that only three relays EW are used for this coding. This is due to the fact that the called subscriber may be comprised either in the first or in the second 500-subscriber group in a given 1000-subscriber group. If the subscriber is in the first 500 group, coding relays EW_a and EW_d en-

ergize, while relays EW_b and EW_d energize if said subscriber is in the second 500 group. It will be noted that relay EW_d energizes regardless of the 500 group to which the called subscriber is connected. For that reason, said relay can be energized before receiving the thousands and the hundreds digits or, stated otherwise, immediately after receiving the three digits making up the code characterizing a local call. This will further be explained in detail in the description that follows.

10 Since the register will have this information once the subscriber has dialed the thousands and the hundreds digits, the 2 relays EW and EX can be energized by sending suitable polarities over certain of the local coding wires mentioned before.

15 After having received the code 965, the register is told that the connection about to be established is a local connection by the energization of relay EF_f, as has already been pointed out. By the passing into operating position of its make-break contact EF_{f1}, relay EF_f prepares the energizing circuit of relay EF_{hi} (Fig. 5), which will subsequently control the starting of the local line-selecting operations. The closing of front contact EF_{f2} completes the energizing circuit of relay EW_d, which pulls up: battery, relay EW_d, local coding wire EW_d, front contact EF_{f2}, ground.

20 The closing of front contact EF_{f3} prepares the energizing circuit of one of the 2 relays EW_a or EW_b. The closing of the five front contacts EF_{f4} . . . EF_{f8} prepares the energizing circuit of 2 of relays EX_a . . . EX_e. The closing of front contact EF_{f9} prepares the energization of relay ED_p. The closing of front contact EF_{f10} grounds wire Iv to fault register ED (Fig. 2). The opening of back contact EF_{f11} prevents any untimely energization of translator-seizure relay EJ_q.

25 As can be seen, coding relay EW_d has just energized, as previously indicated.

30 This relay completes a holding circuit for itself through the closing of its front contact EW_{d1}: battery, relay EW_d, front EW_{d1}, back EF_{c6}, wire Db, cable D, wire Db, front RA_{c1}, ground.

35 The function of the other contacts of this relay will be described subsequently.

40 The calling subscriber will now dial the numerical portion of the called subscriber's number. It will be recalled that this numerical portion is 25—70 in the example chosen at the beginning of this description. At the end of the operation for registering the thousands digit, that is, digit 2, relays ER_b, ER_e, EG_{lm} are energized. The energization of the 2 registering relays ER_b and ER_e entails that of relays EX_b and EX_e. The method of grounding local coding wires Ex_a . . . Ex_e in the register will be explained before describing the energizing circuits of these relays. The 5 local coding wires can be grounded through 5 groups of 2 series front contacts EF_{f4} . . . EF_{f8}, ER_{a2} . . . ER_{e2}. Therefore, a total of 5 sets of 2 front contacts connected in series are provided and connected on the one side to a local coding wire and on the other to ground. These explanations will now allow describing the energizing circuits of

45 relays EX_b and EX_e, which are as follows:

50 (1) Battery, relay EX_b, local coding wire Ex_b, front contact EF_{f5}, front contact ER_{b2}, ground;

55 (2) Battery, relay EX_e, local coding wire Ex_e, front contact EF_{f8}, front contact ER_{e2}, ground.

60 The closing of said front contacts ER_{b2} and ER_{e2} also prepares the code-sending circuit that will be used subsequently in the course of the line-selecting operations and that will be referred to again at that time.

65 Through the closing of their front contacts ER_{b3} . . . ER_{b6}, ER_{e3} . . . ER_{e6}, registering relays ER_b and ER_e prepare the coding circuit that will be used subsequently in the course of the line selection.

70 The energization of relay EG_{lm} has no effect at this time.

75 Relays EX_b and EX_e complete a holding circuit for

themselves through the closing of their front contacts EXb1 and EXe1:

- (1) Battery, relay EXb, front EXb1, back EFc6, wire Db, cable D, wire Db, front RAc1, ground;
- (2) Battery, relay EXe, front EXe1, back EFc6, wire Db, cable D, wire Db, front RAc1, ground.

Through the closing of their front contacts EXb2, EXe2, relays EXb and EXe prepare the code-sending circuits over coding wires *ub* and *ue*. Through the closing of their front contacts EXb3, EXb4, EXe3, relays EXb and EXe prepare the energizing circuit of relay EDp.

At the end of the operations for registering the hundreds digit, digit 5 in the example chosen, relays ESa, ESC, EGop are energized.

Through the closing of their front contacts ESa2 and ESC2, hundreds-digit registering relays ESa and ESC prepare the code-sending circuits that will be used subsequently in the course of the line-selecting operations (Fig. 6). Through the closing of their front contacts ESa4, ESC3, relays ESa and ESC complete the energizing circuit of relay EHh, which pulls up: battery, relay EHh, front ESa4, ESC3, ground over general holding wire *tg*.

The energization of relay EGop entails that of relay RDf, whose energizing circuit is completed through the closing of front EGp2: battery, upper winding of relay RDf, back RDg1, RBn1, wire Rp, cable R, wire Rp, back EFd2, front EGp2, back EDp1, REp1, ground.

The closing of front EGp3 prepares the energizing circuit of relay EDp. The energizing circuit of coding relays EWa or EWb is prepared by the closing of front EGp4.

The energization of relay EHh shows that the called subscriber forms part of the second group of 500 subscribers connected to the 1000 group involved, that is, group 2 in the example chosen. From the foregoing explanations it follows that coding relay EWb should be energized. The energizing circuit of said relay is indeed completed by the closing of front contact EHh1: battery, relay EWb, local coding wire Ewb, front EHh1, EGp4, EFj3, ground. The other contacts of relay EHh are inoperative at this instant.

The energization of relay EWb will allow starting the group-selecting control operations. This relay completes a holding circuit for itself through the closing of its front contact EWb1: battery, relay EWb, front EWb1, back EFc6, wire Db, cable D, wire Db, front RAc1, ground.

Through its front EWb2, coding relay EWb prepares the circuit for the group-selecting control operations. The energizing circuit of relay EDp is completed through the closing of front EWb3 and EWb4: battery, relay EDp, back EWa3, front EWb3, back EWc4, front Ewd4, back EWe3, EXa3, front EXb3, back EXc4, EXd3, front EXe3, EF9, EGp3, ground.

It will be noted that the energization of relay EDp is under the control of 2 series-connected contact pyramids that if need be establish metallic continuity between the energizing winding of relay EDp and front contact EFf9. The purpose of these pyramids is to verify that the 2 relays EW and the 2 relays EX have energized following the reception of the thousands and the hundreds digits. It can easily be verified that the metallic continuity of a pyramid is provided only when 2 out of the 5 relays controlled by it are energized. The metallic continuity is broken in all other cases.

The relay RDf that has just energized forms part of a time device comprising relays RDf, RDg and RDh. This device starts counting time as soon as one or the other of relays RDf and RDg pulls up. The purpose of this device is to verify that the time required to perform each operation controlled by the register is less than a certain value. If that time exceeds said critical value, it may be deduced therefrom that trouble prevents the normal establishment of the connection. Throughout what follows it will be assumed that all the elementary operations required for establishing a local or a toll con-

nexion are performed normally and that relay RDhi therefore never energizes.

Relays RDf and EDg can cause the starting of the time device without distinction. When either one of these relays energizes it starts said device, which then controls a certain elementary operation. When that operation has been effected, the first starting relay releases, while the second energizes. In the course of this switching of the starting relays, the time device is "restored to normal" and accordingly is ready to control the new elementary operation that has just begun immediately after the end of the preceding elementary operation.

The energization of relay RDf prevents the subsequent energization of relay RDg through the opening of back contact RDf1. Make-break contact RDf2 removes the short-circuit from condenser RC3 and completes its charging circuit: battery, resistance RR9, condenser RC3, back contact RDg2, front contact RDf2, ground.

This condenser will be charged gradually, owing to the presence of charge resistance RR9. The sensitive relay RDhi connected to the terminals of this condenser will remain unoperated so long as the voltage at the terminals of the condenser is below a certain predetermined value. This lag will allow providing the control for the energization of relay EDp.

The energization of relay EDp will control the starting of the group selection. The closing of front contact EDp1 short-circuits time condenser RC3, which discharges, thus restoring to normal the time device just mentioned above: ground, front RDf2, back RDg2, condenser RC3, front RDf1, wire Rq, cable R, wire Rq, back EFe2, front EDp1, back REp1, ground.

Relay RDf, having its energizing circuit broken owing to the opening of back contact EDp1, releases with a certain delay due to its lower winding being short-circuited to itself.

The closing of front contact EDp2 completes the energizing circuit of relay EFjk, which pulls up: battery, relay EFjk, back EFe1, front EDp2, back EDm2, EFc4, ground on general holding wire *tg*.

The other contacts of relay EDp are inoperative at this time.

Relay RDf releases after a moment, this meaning that the two groups of coding relays EW and EX have energized properly. The closing of back contact RDf1, completes the energizing circuit of relay RDg, which pulls up: battery, relay RDg, back RDf1, wire Rq, cable R, wire Rq, back EFe2, front EDp1, back REp1, ground.

Condenser RC3 is discharged quickly due to the short-circuiting of its armatures by the closing of back contact RDf2.

The energization of relay RDg will control the starting of a new control cycle by time relay RDhi. The opening of back contact RDg1 prevents untimely energization of relay RDf. Condenser RC3 is freed from the short-circuit and placed under charge by the passing into operating position of make-break contact RDg2: battery, resistance RR9, condenser RC3, front contact RDg2, ground.

Condenser RC3 charges gradually, the relay RDhi connected to its armatures remaining unoperated so long as the voltage at the terminals of said armatures remains below a certain critical value. The time relay has therefore just started a new control cycle, which will measure the time taken up by the group-selecting operations properly speaking.

Since the register now has all the elements required for the group selection, it will send them to a group-selection receiver through a receiver connector. These operations are controlled by relay EFjk, which has just energized. The closing of front contacts EFj1 . . . EFj5 and EFj6 . . . EFj10 prepares the circuit used for sending the selective combinations required for the group selection. The opening of front contact EFj1 prevents the energization of relay EFhi when relay EHed energizes.

after registering the units digit. The closing of front contact EF_k2 prepares the energizing circuit of relay EFe . The closing of front contact EF_k3 applies a battery to wire Fka to tell receiver connector CR subsequently that it must provide the connection of a group-selection receiver. The closing of front EF_k4 completes the energizing circuit of relay ED_n , which pulls up: battery, relay ED_n , front EF_k4 , ground on general holding wire tg .

A ground is applied to wire Is to fault register ED through front contact EF_k5 .

The energization of relay ED_n causes the sending to receiver connector CR of signals that enable it to select a group-selection receiver. The opening of front contact ED_n1 has no effect at the instant under consideration, but will serve subsequently to control the release of relay ED_n . The closing of front contacts ED_n2 and ED_n3 controls the seizure of a receiver connector CR in accordance with a known method. The holding circuit of connection magnet CR_c of receiver connector CR is prepared by the closing of front contact ED_n4 .

The connection of a group-selection receiver will now be effected under the control of the register. This method of connection is known and it will simply be outlined in order to facilitate an understanding of the operation of the register relays controlling the group-receiver connection operations.

The closing of front contact ED_n3 causes the sending of a battery to the set of receiver connectors associated with the register under consideration. As soon as one of these connectors is seized, it causes the sending of a ground over wire Fh , the effect of this being to energize relay EF_{lmn} : ground on wire Fh , back EBq_3 , front ED_n2 , relay EF_{lmn} , battery.

The energization of this relay tells the register that it has just been connected to a receiver connector and that the latter is ready to receive from said register the signals required to allow it to be connected to a receiver. It is well to recall that receiver connector CR allows connecting the register either to a group-selection or to a line-selection receiver. Presently the register is told only that the selection to be made is a group selection. This is characterized by the energization of relay EF_{jk} . By energizing, relay EF_{jk} has prepared information circuits that will allow receiver connector CR to choose the suitable receiver. Said circuits are completed by the energization of relay EF_{lmn} .

The closing of front contacts $EF_1 \dots EF_{10}$ prepares the circuit used for sending the code to the group-selection receiver that is going to be seized by receiver connector CR. Front contacts $EF_{m1} \dots EF_{m10}$ are inoperative at the instant under consideration. The closing of front contact EF_{n1} completes the discrimination circuit that will enable the receiver connector to hunt for and be associated with a group-selection receiver: battery, front EF_k3 , wire Fka , front EF_{n1} , wire Fka , cable F to receiver connector CR.

The seizure-holding circuit of receiver connector CR is completed by the closing of front contact EF_{n4} : battery, front EF_{n4} , wire Fj , cable F to receiver connector CR.

The closing of front contact EF_{n5} applies a ground to wire Ir to fault register ED.

Once the receiver connector is associated with a group-selection receiver, the latter controls the operation of connection magnet CR_c over a circuit not shown. Through the closing of its front contacts $CR_{c1} \dots CR_{c8}$, this magnet provides the connection of wires Fa_2 , Fh_2 , Fc_2 , Fd , Fe , Ff , Er to the corresponding wires (not shown) of the group receiver involved. Connection magnet CR_c completes a holding circuit for itself through its front CR_{c8} : battery, winding of magnet CR_c , front CR_{c8} , ED_{n4} , ground.

The receiver thereupon registers the selective combinations needed for the group selection at the proper registering relays and in accordance with a known method over the following circuits:

- (1) Ground, front EW_{b2} , EF_{j2} , wire db , front EF_{l7} , wire Fmb , cable F to receiver connector CR;
- (2) Ground, front EW_{d2} , EF_{j4} , wire dd , front EF_{l9} , wire Fmd , cable F to receiver connector CR;
- (3) Ground, front EX_{b2} , EF_{j7} , wire ub , front EF_{l2} , wire Flb , cable F to receiver connector CR;
- (4) Ground, front EX_{e2} , EF_{j10} , wire ue , front EF_{l5} , wire fle , cable F to receiver connector CR.

To be able to connect itself to one of the two markers associated with the group-selecting means to which the calling subscriber has been connected during the hunting for the calling line, the receiver must know the identity of said group-selecting means. This identity is sent to the receiver in accordance with a known method by sending a special polarity over the discrimination wire Ac_2 coming from the group-selecting means to which the calling subscriber has access. This polarity is sent by the register and by the receiver connector to the group-selection receiver over the following circuits: wire Ac_2 brought to a special potential, front EC_{c6} , wire Bc_2 , cable B, wire Bc_2 , back RA_{p1} , wire Fc_2 , cable F to the group-selection receiver involved through receiver connector CR.

Having now received all this information, the group-selection receiver will be able to send it to one of the two markers associated with the group-selecting means involved. The marker tells the register that it has received all the information required for the group selection, and that this group selection has just been effected normally, by connecting battery to wire Fe through receiver connector CR, the effect of this being to energize relay EBq : ground, upper winding of relay EBq , back EBq_2 , wire Fe grounded by the group-selection receiver through receiver connector CR.

Relay EBq will control the receiver-connector's releasing operations. Relay EBq completes a holding circuit for itself through the closing of its front EBq_1 : ground, lower winding of relay EBq , front EBq_1 , battery on wire Ff applied by the group receiver through receiver connector CR.

The closing of front contact EBq_2 completes the energizing circuit of releasing relay ED_m , which pulls up: ground, relay EC_1 , right-hand winding of relay ED_m , rectifier EQ_3 , wire Re , front EBq_2 , wire Fe connected to battery across a high resistance in the group-selection receiver and through receiver connector CR.

Marginal relay EC_1 remains unoperated owing to the high resistance switched in by the group-selection receiver involved.

Through the opening of its back contacts EBq_4 and EBq_3 , relay EBq breaks the holding circuit of receiver connector CR and of relay EF_{lmn} , which releases.

Relay ED_m completes a holding circuit for itself through the closing of its front contact ED_{m1} : battery, left-hand winding of relay ED_m , front EF_k4 , ground on general holding wire tg .

The opening of back ED_{m2} removes the short-circuit from relay EFe , which releases, while relay EF_{jk} holds in series with said relay EFe : battery, relay EF_{jk} , front EF_k2 , back EFe_3 ; relay EFe , wire Rg , back EF_{c4} , ground on general holding wire tg .

The other contacts of relay ED_m are inoperative at this time.

The release of relay EF_{lmn} breaks the code-sending circuits that have just been used for the group selection.

Relay EFe controls the ending of the group-selection operations. The passing into operating position of its make-break contact EFe_1 prepares the energizing circuit of relay EF_{hi} and prevents further energization of relay EF_{jk} . The time circuit is restored to normal through the opening of back contact EFe_2 , the effect of this being to break the energizing circuit of relay RD_g , which releases with a slight delay. Relay EFe completes a holding circuit for itself through the closing of its make-break contact EFe_3 : battery, resistance ER_7 , front

EF_{e3}, relay EF_e, wire R_g, back EF_{c4}, ground on general holding wire *tg*.

The opening of back contact EF_{e3} breaks the energizing circuit of relay EF_{jk}, which releases.

The release of relay EF_{jk} prepares the energizing circuit of relay EF_{hi} through the closing of its back contact EF_{k1}. Relay ED_n releases owing to the break in its energizing circuit caused by the opening of front contact EF_{k4}. The ground applied to wire I_s to fault register ED is removed by the opening of front contact EF_{k5}.

The release of relay ED_n entails the release of connection magnet CR_c of receiver connector CR through the opening of front contact ED_{n4}.

The receiver connector, released by the release of magnet CR_c, breaks the energizing circuit of relays EB_q and ED_m, which release, thereby marking the end of the group-selecting operations.

The register will now control the line-selecting operations as soon as the calling subscriber has dialed the hundreds, tens and units digits of the numerical portion of the called subscriber's number.

It will be recalled that the called subscriber's number is 965-25-70. Once the calling subscriber has dialed the last two digits, namely 7 and 0, the following relays energize:

- (1) For the tens digit 7: ET_c, ET_d, EH_{ab};
- (2) For the units digit 0: EU_b, EU_d, EH_{de}.

The energizing method of these relays, which is identical with that of relays EO_a, EO_d and E_{lc}_d, which has already been explained, will not be described.

Through the closing of their front contacts ET_{c2} and ET_{d2} (Fig. 5), tens-registering relays ET_c and ET_d prepare certain code-sending circuits involved in the line selection. Relay EH_{ab} has no effect at this time.

Through the closing of their front contacts ES_{b2} and ES_{d2}, units-registering relays ES_b and ES_d prepare the code-sending circuits involved in the line selection.

Relay EH_{de} tells the register that the calling subscriber has just dialed the last digit of the called subscriber's number. Through the closing of its front contact EH_{e1}, relay EH_{de} completes the energizing circuit of relay RD_f of the time device: battery, upper winding of relay RD_f, back RD_{g1}, RB_{n1}, wire R_p, cable R, wire R_p, back EF_{d2}, front EH_{e1}, EF_{e2}, ED_{p1}, back RE_{p1}, ground.

The supply circuit of pulse counter NR is definitely broken by the opening of back contact EH_{e2}, this rendering it insensitive to the arrival of new pulses should the calling subscriber dial additional digits. The closing of front contact EH_{e3} (Fig. 2) completes the energizing circuit of the primary winding of transformer RC_{cd}: ground, primary winding of transformer RC_{cd}, front EH_{e3}, back EE_{o5}, waiting-tone generator RG₁, ground.

Relay EF_{hi}, controlling the starting of the line-selecting operations, pulls up, its energizing circuit having just been completed by the closing of front contact EH_{e4} (Fig. 5): battery, relay EF_{hi}, front EH_{e4}, back EF_{d1}, front EF_{j1}, back EF_{k1}, front EF_{e1}, ED_{p2}, back ED_{m2}, wire R_g, back EF_{c4}, ground on general holding wire *tg*.

The timing device will now control in accordance with a method already described the building-up time of the line-selecting operations.

The energization of the primary winding of transformer RC_{cd} causes the sending through the calling subscriber's loop of a special waiting tone that will tell the calling subscriber that the register has received the called subscriber's number properly and that the operations involved in hunting for the latter subscriber are in progress. The circuit used for sending this tone has already been described at the beginning of this description.

Relay EF_{hi} controls the line-selecting operations as has just been stated.

Through the closing of its contacts EF_{h1} . . . EF_{h5}, relay EF_{hi} prepares the circuits used for sending the code corresponding to the tens digit. Through the closing of

its front contacts EF_{h6} . . . EF_{h10}, relay EF_{hi} prepares the circuits used for sending the code corresponding to the units digit. Through the closing of its front contacts EF_{i1} . . . EF_{i5}, relay EF_{hi} prepares the circuits used

- 5 for sending the code corresponding to the hundreds digit. The energizing circuit of relay EF_d is prepared by the closing of front contact EF_{i6}. Front contact EF_{i7} prepares the discrimination circuit that will allow hunting for a line-selection receiver. Front contact EF_{i8} completes the energizing circuit of relay ED_n, which pulls up: battery, relay ED_n, front EF_{i8}, ground on general holding wire *tg*.
- 10

The called-subscriber category discrimination circuit is prepared by the closing of front contact EF_{i9}. Front contact EF_{i10} is not used for local calls. A ground is applied to wire I_t to fault register ED by the closing of front contact EF_{i11}.

The sequence of operations that develop in the course of the line selection will be explained before proceeding with this description.

- 20 When the register is connected to a receiver connector, it must furnish it a special signal telling it that it must be associated with a line-selection receiver. In a 10,000-line exchange such as involved in the present description, 25 the line-selection receivers are divided into 2 groups, each having access to one half of the set of 2 markers associated with a line-selecting means. Stated otherwise, the subscribers of a 10,000-line exchange are divided into 2 groups of 5,000 subscribers, each 5,000-subscriber group 30 being associated with one half of the line-selection receivers provided in said exchange. Hence, the register must give the receiver connector a double signal, telling it that it must be associated with a line-selection receiver and that said receiver forms part of the first or of the 35 second 5,000-subscriber group of the exchange involved.

The two discrimination wires F_{kb} and F_{kc} (Fig. 7) are used for that purpose. The grounding of one or the other of these wires tells receiver-connector CR that it must be associated with a line-selection receiver. In addition, depending on whether the called subscriber belongs to the first or to the second 5,000-subscriber group, the ground is applied either to wire F_{kb}, for called subscribers connected to the thousands 0, 1, 2, 3, 4, or to wire F_{kc}, for called subscribers connected to the thousands 5, 6, 7, 8, 9. This grounding is effected by a set of 20 decoding contacts ERA_{3/5}, ERB_{3/5}, ERC_{3/5}, ERD_{3/5}, ERE_{3/5} belonging to the 5 thousands-digit registering relays ERA . . . ERE. The operation of these contacts has already been mentioned before. Suffice it to recall that the thousands digit of the called subscriber's number is the digit 2, this bringing about the energization of registering relays ER_b and ERE and further the closing of front contacts ER_{b3} and ERE₄, which thus complete the grounding circuit for discrimination wire F_{kb}, which will 55 subsequently be used to tell receiver connector CR:

- (1) That it must hunt for a free line-selection receiver;
- (2) That the hunting must be done in the group of line-selection receivers allotted to the first 5,000-subscriber group.

60 Once a line-selection receiver has been seized by receiver connector CR, it must be connected to one of the two markers associated with the line-selecting means to which the called subscriber is connected. The register knows the identity of the line-selecting means to which the latter is connected and can therefore send it directly to the line-selection receiver that has just been seized, to allow said receiver to be connected to one of the two markers associated with the line-selecting means involved. It is well to note here that, contrary to what happened

- 65 for the group selection, the identity of the line-selecting means is sent directly to the line-selection receiver from the register and not from the line-selecting means via said register as was done for the group selection. This latter is due to the fact that the register does not know the 70 identity of the group-selecting means to which the calling 75

subscriber has been connected in the course of hunting for the calling line, while it does know the identity of the line-selecting means to which the called subscriber is connected.

In order to be able to connect itself to one of the two markers associated with the line-selecting means to which the called subscriber is connected, the line-selection receiver must know two things: the 1000 group and the 500 group to which the called subscriber is connected.

The information is sent to said line-selection receiver over wires *E_{da/e}* and *E_{ca/e}*. The hundreds-code sending wires *E_{ca}* serve two purposes:

(1) To tell the line-selection receiver the 500-subscriber group to which the called subscriber is connected;

(2) To tell one of the two markers of the line-selecting means to which the called subscriber is connected the hundreds to which said subscriber belongs.

In order to provide the line selection the marker must know the last two digits of the numerical portion of the called subscriber's number, that is, the tens and the units digits. This information is sent in coded form over the two groups of five wires *da/e* and *ua/e*.

It will be recalled that the numerical portion of the called subscriber's number is 25—70, this corresponding to the energization of the following registering relays:

- (1) For thousands digit 2—relays *ER_b*, *ER_e*;
- (2) For hundreds digit 5—relays *ES_a*, *ES_c*;
- (3) For tens digit 7—relays *ET_c*, *ET_d*;
- (4) For units digit 0—relays *EU_b*, *EU_d*.

These relays ground the code-sending wires as follows:

(1) Ground, front *ER_{b2}*, thousands-code sending wire *E_{db}*, cable *E*, wire *E_{db}* to receiver connector *CR*;

(2) Ground, front *ER_{e2}*, thousands-code sending wire *E_{de}*, cable *E*, wire *E_{de}* to receiver connector *CR*;

(3) Ground, front *ES_{a2}*, wire *E_{ea}*, cable *E*, wire *E_{ea}*, front *EF_{i1}*, hundreds-code sending wire *ca* to receiver connector *CR*;

(4) Ground, front *ES_{c2}*, wire *E_{ec}*, cable *E*, wire *E_{ec}*, front *EF_{i3}*, hundreds-code sending wire *cc* to receiver connector *CR*;

(5) Ground, front *ET_{c2}*, *EF_{h3}*, tens-code sending wire *dc* to receiver connector *CR*;

(6) Ground, front *ET_{d2}*, *EF_{h4}*, tens-code sending wire *dd* to receiver connector *CR*;

(7) Ground, front *EU_{b2}*, *EF_{h7}*, units-code sending wire *ub* to receiver connector *CR*;

(8) Ground, front *EU_{d2}*, *EF_{h9}*, units-code sending wire *ud* to receiver connector *CR*.

These explanations allow continuing the description of the development of the line-selecting operations. It will be recalled that the energization of relay *EF_{hi}* has entailed that of relay *ED_n* through the closing of front contact *EF_{i8}*. As from the moment of energization of relay *ED_n*, the general operation of the register will be the same as already described in connection with the group selection. Relay *ED_n* controls the seizure of a receiver connector *CR* for example. The latter in turn is connected to a line-selection receiver, which is associated with one of the two markers of the line-selecting means to which the called subscriber is connected. When the receiver connector has found said receiver, relay *EF_{lmn}* pulls up, while connection magnet *CR_c* is energized. When the receiver has registered the coded information that will allow hunting for the called subscriber among the 500 lines comprised in the line-selecting means involved, relay *EB_q* pulls up, thereby telling the register that the line-selecting operations have just ended. Relay *ED_m* pulls up immediately. The pulling up of this relay will this time cause that of relay *EF_d* in a manner identical with the one described in connection with the pulling up of relay *EF_e* during the group-selecting operations.

The pulling up of relay *EF_d* prepares the energizing circuit of relay *RA_p* through the closing of front contact *EF_{d1}*. By the passing into operating position of its make-

break contact *EF_{d2}*, the time device is "restored to normal" in accordance with a method already described and then immediately placed in counting position to control the release of the register. By the passing into operating position of make-break contact *EF_{d3}*, relay *EF_d* completes a holding circuit for itself and opens the energizing circuit of relay *EF_{hi}*, which releases: battery, resistance *ER₆*, front *EF_{d3}*, relay *EF_d*, wire *R_g*, back *EF_{c4}*, ground on general holding wire *tg*.

10 In accordance with a known method already described, the release of relays *EF_{hi}* and *ED_n* entails that of relay *EB_q* and the release of translator connector *CR*.

The release of relay *EF_{hi}* further entails that of relay *ED_m*.

15 The release of relay *ED_m* entails the pulling up of relay *RA_p*, whose energizing circuit is completed by the closing of back contact *ED_{m2}*: battery, lower winding of relay *RA_p*, wire *R_h*, cable *R*, wire *R_h*, front *EF_{d1}*, *EF_{f1}*, back *EF_{k1}*, front *EF_{e1}*, *ED_{p2}*, back *ED_{m2}*, wire *R_g*, back *EF_{c4}*, ground on general holding wire *tg*.

20 Relay *RA_p* controls the release of the register. Through the closing of its front *RA_{p3}*, it applies a ground to wire *Io* to fault register *ED*. Through the opening of its back contact *RA_{p4}*, the energizing circuit of register-holding relay *RC_b* is opened, thereby releasing this relay.

The opening of back contact *RC_{b1}* breaks the ground on test wire *B₁₁*, the effect of this being to establish metallic continuity in the register connector between the calling subscriber and the group-selecting means. The opening 30 of front contact *RC_{b4}* breaks the energizing circuit of loop relay *RA_{ab}*, which releases, together with the associated relay *RC_a*.

The release of relay *RC_a* entails the release of relay *RAC_d*, which is delayed due to the short-circuit of its upper winding.

35 After a moment, relay *RAC_d* releases in turn and removes the ground from general holding wire *tg* owing to the opening of front contact *RAd2*, this causing the release of all the relays that were holding over this wire.

40 Code relays *EW* and *EX*, which were holding over wire *Db*, release in turn owing to the opening of front contact *RAc1*. The release of relay *RAC_d* further causes the release of register finder *CR* owing to the opening of front contact *RAd3*. The register is thus released.

45 The operations that follow the metallic connection of the calling subscriber to the group-selecting means do not come within the scope of the present invention and will not be described.

It will now be assumed that the calling subscriber dials 50 a number corresponding to an area call. It will be assumed by way of example that he dials 828—25—70. In this number, 828 constitutes the so-called code, while 25—70 represents the numerical portion of said number.

The seizure of the register and the registering of the 55 digits dialed by the subscriber are effected the same way as described in connection with a local call. When the subscriber is through dialing the third code-digit, relay *EF_f* does not pull up, since its energizing circuit can be completed only when the code dialed is 965, as has previously been pointed out. It is known that relay *EG_{ij}* pulls up after the registering of the third code-digit. The operation of this relay has already been explained. It will be recalled that front *EG_{j1}* was inoperative owing to the pulling up of relay *EF_f*, which had thereby opened

60 back contact *EF_{f11}*, thus preventing the energization of relay *EJ_q*. In the case of an area call, relay *EF_f* remains unoperated. From this it follows that the energizing circuit of relay *EJ_q* is completed through the closing of front contact *EG_{j1}*, the relay therefore pulling up: battery, relay *EJ_q*, back *EF_{f11}*, *ED_{p4}*, *ED_{q2}*, *EE_{q1}*, *EEm3*, front *EG_{j1}*, wire *R_g*, cable *R*, wire *R_g*, front *EF_{c4}*, ground on general holding wire *tg*.

65 Before considering the operation of relay *EJ_q*, it will be noted that none of code relays *EW_{a/e}* and *EX_{a/e}* pulls up, since relay *EF_f* is unoperated and its front con-

tacts EF_{f3} . . . EF_{f8} are open. The pulling up of these relays depends in fact upon the area connection wanted and accordingly should be under the control of the translator.

How a translator is seized by the register will not be described. It will be recalled simply that the register is connected to a translator by a translator connector, represented in simplified form by a rectangle referenced CT in Fig. 6. Connection magnet CT_c is shown within this rectangle. The energizing and holding circuits of this magnet are not shown. The wires connecting register E to translator T are grouped in a cable referenced E. This cable passes through translator connector CT, whose connection contacts are shown as a single front contact referenced CT_{n1/10}. The method of seizing the translator has moreover been described in Patent No. 1,069,160, filed by the two applicants on December 18, 1952.

For reference, it is recalled that the registers of the exchange involved are divided into a certain number of groups, each group having access to the 2 translators of said exchange through translator connectors.

When a register must be connected to a translator, it is brought into calling position in the group to which it belongs. This group becomes "calling" in turn, hunts for a free translator and connects itself to it through the corresponding translator connector.

The pulling up of relay EJ_q causes, over circuits not shown, the operation of connection magnet CT_c of translator connector CT. The seizure of the translator is effected by grounding wire Eh, this entailing the energization of relay TC_k (Fig. 8): battery, upper winding of relay TC_k, wire Eh, cable E through receiver connector CT, wire Eh, front EJ_{q1}, ground.

The energizing circuit of relay RD_f (Fig. 3) of the timing device is completed by the closing of front contact EJ_{q2}: battery, upper winding of relay RD_f, back RD_{g1}, RB_{n1}, wire Rp through cable R, back EF_{d2}, front EJ_{q2}, back ED_{p1}, RE_{p1}, ground.

Through the closing of front contact EJ_{q3} (Fig. 2) a ground is applied to wire I_x to fault register ED.

The pulling up of relay TC_k busies the translator on the banks of all the translator connectors, this busying being provided by contacts not shown of said relay TC_k.

The translator may be regarded as being busy as soon as one of the relays making up the translator equipment pulls up. For that reason, as soon as a relay of the equipment of said translator pulls up, it completes a holding circuit for relay TC_k, this holding circuit further involving the two windings of said relay TC_k. Stated otherwise, there will be as many holding contacts of relay TC_k as there are relays whose pulling up it is desired to control, all these contacts being of course connected in parallel between the ground and wires C_{k1} or C_{k2}. For readily understandable reasons of simplification, all the holding contacts associated with wire C_{k2} have been shown as a single front contact bearing the following in parentheses: (See Table 1.)

This table shows the references of all the holding contacts of relay TC_k. These contacts will further be mentioned at the proper time in the description that follows.

The timing device, which has just been started by the closing of front contact EJ_{q2}, will control the answering time of translator T.

The register contains a special relay EEn (Fig. 6) that pulls up in case of national calls (the energizing circuit of this relay will be described subsequently). In the example here chosen, the connection wanted is an area connection and hence relay EEn remains unoperated. It follows from this that make-break contact EEn2 directs the ground on wire El to translator T. As soon as said translator is connected to the register through translator connector CT, the circuit of relay TE_k is completed (Fig. 8): battery, relay TE_k, wire El through cable E and translator connector CT, back EEn2, ground.

The pulling up of relay TE_k tells translator T that it is going to receive the number of an area call and that therefore it must perform the translation operations corresponding to said area call.

Through the closing of its front contact TE_{k1}, relay TE_k completes the holding circuit of relay TC_k, as follows from the above-mentioned Table I. The energizing circuit of the 9 relays TE_{b/j} is prepared by the closing of the 9 front contacts TE_k/2/10.

As previously pointed out, the seizure of the translator in the case of area calls is effected after reception of the code, that is, the first three digits dialed by the calling subscriber.

Reference to the above-mentioned table will show that following reception of the code, 828 in the example chosen, the following registering relays are pulled up (Fig. 4):

- (1) Relays EO_d, EO_e for the 1st digit (8);
- (2) Relays EP_b, EP_e for the 2nd digit (2);
- (3) Relays EQ_d, EQ_e for the 3rd digit (8).

The register must send the translator the number it has just received from the calling subscriber in the form of numerical pulses. To save time, this sending is done in coded form in a manner identical with the one described with reference to the sending to the registering relays of the digits stored by the pulse-counting relays NR. This sending is done by 3 groups of 5 wires referenced as follows (Fig. 8):

- (1) Wires Eaa/e for digit P;
- (2) Wires Eba/e for digit Q;
- (3) Wires Eca/e for digit R.

Each 5-wire group has a set of 5 decoding relays in translator T (Fig. 8). These relays are shown separately and referenced TA_a . . . TA_e for those concerning the first group of 5 wires Eaa . . . Eae, corresponding to the sending of the number's first digit (P). For the other 5-wire groups, the corresponding decoding relays are shown as a single relay referenced for example TA_{f/j} for the second group of 5 sending wires referenced Eba/e.

Code-sending wires Eaa/e . . . Eac/e are all under the control of front contacts EOa_{2/e2}, EPA_{2/e2}, EOa_{2/e2} of registering relays EO_{a/e}, EP_{a/e}, EQ_{a/e} (Fig. 6). From this it follows that when the translator is connected to the register, the decoding relays of said translator "duplicate" the registering relays of equipment E.

It will be recalled that in the example chosen the code dialed by the calling subscriber is 828. When the translator is connected to the register, the energizing circuits of the decoding relays associated with the sending wires corresponding to the registering relays that have energized following the reception of the called subscriber's number are completed as follows:

(1) Battery, relay TAd, wire Ead through cable E and translator connector CT, front EO_{d2}, back EL_{q1}, ground;

(2) Battery, relay TAe, wire Eae through cable E and translator connector CT, front EO_{e2}, ground over a circuit already described.

Decoding relays TAg, TAj, TBd, TBe pull up in similar fashion.

Each group of 5 decoding relays has a decoding pyramid comprising 10 outgoing wires each capable of being grounded. When 2 decoding relays of one group pull up, an outgoing wire of the associated decoding pyramid is grounded. The operation of these pyramids, which are standard use in telephone switching, will not be described in detail. With the exception of the first, that is, the one corresponding to the first code-digit (P), all these pyramids are represented in simplified form by rectangles, referenced D2C, D3C, these being the decoding pyramids for the 2nd and 3rd digits of the code P—Q—R. Inside each rectangle are shown 2 front contacts in series, these 2 contacts representing schematically the 2 stages of decoding contacts comprised in each decoding pyra-

mid. The first decoding pyramid is shown in detail in order to illustrate the principle employed for the embodiment of said pyramids.

It will be assumed throughout what follows that the codes whose first digit is the digit 1 involve special services, which will be discussed subsequently. However, the digit 1 can be used for national calls requiring 8-digit numbers. From this it follows that for area calls, as is the case in the present description, the digit P will always be comprised between 2 and 10. For that reason, out of the 10 decoding-pyramid outgoing wires referenced **Ja1/10**, only 9 (**Ja2/10**) are used for the translations required for area calls. These 9 outlets together with the 10 outlets belonging to decoding pyramid D2C allow obtaining 90 possible combinations with the first two digits of the codes used for area calls. In order to obtain these 90 selective combinations, the 9 wires **Ja2/10** have 9 relays referenced **TEb/j**, each equipped with 10 front contacts **TEb2/11 . . . TEb11**, this representing a total of 90 front contacts for the 90 selective combinations possible with the first two digits of the code.

Each outgoing wire of the second decoding pyramid is multiplied to 9 front contacts of the 9 relays **TEb/j**. Thus, for example, the first wire (**Ka1**) of the second contact-pyramid is multiplied to the 9 front contacts **TEb2 . . . TEb9**, the second wire (**Ka2**) is multiplied to the 9 front contacts **TEb3 . . . TEb9** and so on. These front contacts are shown as a single front contact referenced **TEb/j2/11** at which terminates a cable referenced **Ka1/10**. Thus are obtained 90 outgoing wires shown as a cable referenced **Kb10/99**, each wire corresponding to a particular combination of the first two digits (P and Q) of the code. These wires terminate at 90 terminals of an allotter RT. These terminals are shown as a single terminal referenced **B10/99**.

Each outgoing wire **La2/10** of decoding pyramid D3C has one decoding relay **TFa . . . TFj** in Fig. 8. These relays are used when the number dialed by the calling subscriber requires the translation of more than 2 of the digits making up said code.

Before proceeding with this description, we shall resume the operation of the translator after the pulling up of decoding relays **TAd**, **TAe**, **TAg**, **TAj**, **TBd**, **TBe**. These relays complete holding circuits for translator-busy relay **TCk** by the closing of their front contacts **TAd7**, **TAe2**, **TAg7**, **TAj2**, **TBd7**, **TBe2**, as follows from Table I of the above-mentioned figure.

The closing of the above-mentioned front contacts will further complete the energizing circuit of relays **TTb** and **TTf**, which pull up:

(1) Battery, relay **TTb**, back **TTa1**, wire **Ck2**, ground over a circuit already described;

(2) Battery, relay **TTf**, back **TTe1**, **TTd1**, **TTc1**, wire **Ck2** grounded.

In order to ensure proper operation of the decoding relays, control pyramids are provided, shown in the drawing as rectangles enclosing a front contact. The pyramids, referenced **K1C . . . K3C**, provide control for the groups of decoding relays **TAa/e . . . TBa/e**. Such pyramids have already been described with reference to the control of relays **EWa/e**, **EXa/e** in the course of the preceding description, which concerned a local call. Suffice it to recall that for a given group of decoding relays, the associated control pyramid verifies that 2 decoding relays of the group involved are pulled up, something that is represented in this case by the closing of the front contact shown within the rectangle representing said control pyramid. From each control pyramid issues a wire **d1 . . . d3** connected by cables and contacts not shown to fault register **ED** (Fig. 2), which was discussed in connection with local calls.

In the present case, following normal operation of decoding relays **TAd**, **TAe**, **TAg**, **TAj**, **TBd**, **TBe**, wires **d1**, **d2**, **d3** are grounded by control pyramids **K1C**, **K2C**, **K3C**. The decoding of the code 828 causes the ground-

ing of wires **Ja8**, **Ka2**, **La8** by the corresponding decoding pyramids.

The grounding of wire **Ja8** causes the energization of relay **TEh** over the following circuit: battery, relay **TEh**, front **TEk8**, wire **Ja8**, front **TAe6**, **TAd4**, ground.

The grounding of wire **La8** entails the energization of relay **TFh**: battery, relay **TFh**, wire **La8**, third-digit decoding pyramid **D3C**, ground.

The pulling up of relay **TEh** causes the grounding of **10** wire **Kb82**, corresponding to the combination of the first two digits (P and Q) of the code dialed, that is, the digits 8 and 2 in the example chosen: terminal **B82**, wire **Kb82**, front **TEh3**, second-digit decoding pyramid **D2C**, ground.

15 It is well to point out further that relay **TEh** completes a holding circuit for **TCk** in accordance with a known method (see Table I of Fig. 8).

In the present case the translator has just received from the register the first three digits (P—Q—R) making **20** up the code of the called subscriber's number. This reception is characterized in the final analysis by the grounding of terminal **B82**, corresponding to the following specific values of the digits P and Q: **P=8, Q=2**.

It has been pointed out that the reception of the digit **25** **R** caused the pulling up of relay **TFh**. In the example here chosen, the pulling up of this relay is inoperative, as will be seen from the explanations that follow.

It is known that in automatic telephony the routing of a call from the originating exchange to the terminating **30** exchange or to a tandem exchange requires the translation of a certain number of digits making up the called subscriber's number. Depending upon the case, the translation necessary will involve 2, 3 or even more digits. However, in most cases, the translation of 2 or 3 digits **35** is standard practice. For that reason, in the case of area calls, the register waits until it has received the first three digits of the called subscriber's number and, once it has received them, seizes a translator and sends it the three digits it has just received. According to the fore-

40 going, the sending to the translator of the number's first three digits is therefore superfluous where the connection requires the translation of but two digits.

The translation of any selective combination (2 digits or 3 digits) should allow the translator to send the register **45** 3 signals:

(1) A signal allowing the group selection to be made;
(2) A signal determining the number of digits of the called subscriber's number that must be sent to the terminating or to the tandem office;

50 (3) A toll signal that will subsequently allow control of the calling subscriber's meter.

In order to save time, the sending of said signals from the translator to the register is done in coded form. The code used is identical with the one already mentioned in **55** the course of the present description.

As already indicated, the signals required for the group selection comprise 2 elements, one for the energization of 2 of the 5 relays **EWa/e** and the other for the energization of 2 of the 5 relays **EXa/e**, the signals being sent **60** to the two above-mentioned groups of relays by two 5-wire groups referenced **Ewa/e**, **Exa/e**.

Similarly, the signals required for determination of the number of digits to be resent, and for determination of the tolls, are received at the register by 2 groups of **65** 5 relays referenced **EYa/e**, **EZa/e**, whose operation will be explained subsequently. The control of these relays is effected from the translator by two 5-wire groups referenced **Eya/e** and **Eza/e**.

For a given route, the translator must therefore send **70** two polarities over each 5-wire group controlling relays **EWa/e**, **EXa/e**, **EYa/e**, **EZa/e**. This result is obtained by providing as many route relays as there are different outgoing groups in the exchange involved. When one of these relays is energized, it provides control for a certain number of auxiliary relays that, through their

front contacts, cause the sending of the necessary polarities over the above-mentioned sending wires.

These route relays are referenced TKa/h in Fig. 8 and have their energizing windings connected to 8 input terminals referenced Ea/h . The number of these relays is further in no way limitative and may be increased if necessary.

In the final analysis, the translation of a code corresponding to a given area call is therefore characterized by the pulling up of a particular route relay corresponding to said wanted direction.

It follows from this that in the case of a call requiring the translation of 2 digits, it is therefore sufficient to connect the energizing windings of certain route relays to certain combination terminals $B10/99$ corresponding to the 90 combination wires $Kb10/99$.

In the example chosen, the code 828 corresponds precisely to an area call requiring the translation of only the first two digits, 8 and 2. It will be recalled that the selective combination for these first two digits is characterized by the grounding of terminal $B82$. The route relay provided to determine the selective combinations required for the routing of such a call is relay TKe . For this purpose, allotter RT comprises a jumper directly connecting output terminal $B82$ to input terminal Ee . This jumper is shown as a dotted line in said allotter RT: battery, relay TKe , terminal Ee , jumper in allotter RT, terminal $B82$, wire $Kb82$, front $TEh3$, wire $Ka2$, second-digit decoding pyramid $D2C$, ground.

Thus, as soon as output terminal $B82$ is grounded, route relay TKe pulls up and sends the register the signals required for the routing of the wanted area call. Through the closing of its front contact $TKe11$, this route relay completes a holding circuit for translator-busy relay TCK ; battery, upper winding of relay TCK , front $TKe11$, ground.

In order to control the sending to the register of the signals required for the routing of the call, each route relay comprises, in addition to the holding contact of relay TCK , 10 front contacts referenced $TKa1/h1$, $TKa2/h2 \dots TKa10/h10$. The first nine contacts are assembled into three 3-contact groups. Three wires referenced $Twa1/h1$, $Txa2/h2$, $Tya3/h3 \dots Twa7/h7$, $Txa8/h8$, $Tya9/h9$ issue from each 3-contact group thus formed. Also, there are 8 wires referenced $Tza10/h10$ for the 8 front contacts $TKa10/h10$. Thus are obtained 80 wires terminating at 80 output terminals of incoming allotter RT. These terminals are referenced $G1/80$ and are associated with the 80 outgoing wires $Twa1 \dots Tzh10$ in the following order:

Wire $Twa1$ —terminal $G1$
Wire $Txa2$ —terminal $G2$
Wire $Txb1$ —terminal $G11$
Wire $Txb2$ —terminal $G12$
Wire $Tyh9$ —terminal $G79$
Wire $Tzh10$ —terminal $G80$

The wires whose reference number begins with the letters Tw are intended to control the auxiliary relays controlling register relays EWa/e . Likewise, the outgoing wires whose reference number begins with the letters Tx , Ty , Tz control the auxiliary relays controlling the groups of relays EXa/e , EYa/e , EZa/e of register E (Fig. 4).

The auxiliary relays controlling relays EWa/e , EXa/e , EYa/e , EZa/e are referenced $TPa \dots TPe$, $TQa \dots TQe$, $TRa \dots TRE$, $TSa \dots TSe$. They are divided into four 5-relay groups, each group controlling relays EWa/e , EXa/e , EYa/e , EZa/e . Each auxiliary-relay group is controlled by 10 incoming wires referenced as follows:

(1) Wires $Wa1 \dots Wa10$ associated with relays $TPa \dots TPe$;

- (2) Wires $Xa1 \dots Xa10$ associated with relays $TQa \dots TQe$;
- (3) Wires $Ya1 \dots Ya10$ associated with relays $TRa \dots TRE$;
- (4) Wires $Za1 \dots Za10$ associated with relays $TSa \dots TSe$.

Each control wire of a given auxiliary-relay group is connected to an input terminal of allotter RT and to battery through the windings in series of 2 auxiliary relays. The input terminals are referenced $Hw1/10$ for the first group of auxiliary relays $TPa \dots TPe$, $Hx1/10$ for the second and so on. From this it follows that the grounding of any one of input terminals $Hw1/10$, $Hx1/10$, $Hy1/10$, $Hz1/10$ causes the pulling up of 2 auxiliary relays corresponding to that terminal.

Each auxiliary relay has 2 front contacts, the one completing the holding circuit for relay TCK , the other grounding one of the control wires of one of the relays $EWa/e \dots EZa/e$ of register E (Fig. 4). In addition, control pyramids KW , KX , KY , KZ have been provided, which are similar to others previously described and which allow checking the proper operation of the above auxiliary relays. Whenever 2 relays are pulled up in each auxiliary-relay group, the corresponding control pyramid provides the grounding of the corresponding control wire connected by circuits not shown to fault register ED (Fig. 2). These control wires are referenced $d6 \dots d9$ in Fig. 9.

It follows from these explanations that in order to send to the register the signals required for the routing of any area call it suffices to jumper 4 output terminals associated with a given route relay, that is, with the one pulling up following the translation of a predetermined code, to 4 input terminals each controlling 2 auxiliary relays.

It is well to recall that each route relay has its front contacts divided into three 3-contact groups and one 1-contact group. Each 3-contact group can control 6 auxiliary relays (3 times 2 auxiliary relays chosen from the groups of relays TPa/e , TQa/e , TRa/e). On the other hand, the single front contact belonging to the fourth group can control only 2 auxiliary relays chosen from the group of relays TSa/e . The auxiliary relays belonging to groups TPa/e , TQa/e , TRa/e control relays EWa/e , EXa/e , EYa/e . These relays supply the register the necessary elements that enable it to control the routing of the call, that is, the control of the group selection and indication of the number of digits to be sent to the distant exchange. Now, one route relay can control 3×6 auxiliary relays or 3×2 auxiliary relays per category.

Since 6 auxiliary relays supply the register the elements required for the routing of the call, it follows that a given route relay can control a number of routes through the set of discrimination contacts. These routes are arranged however to provide the termination of one and the same call, except where transfer must be made to an operator. In certain cases it is indeed necessary to provide a number of routes for the routing of a given call. Such is the case, for example, when reroutings are provided for a connection between two exchanges.

On the other hand, it will be noted that a route relay can control only one toll, since it has only one front contact capable of controlling 2 auxiliary relays out of the five making up relay groups TSa/e . This is due to the fact that in the event of rerouting the toll chargeable to the calling subscriber must be the same as the one that would have been charged to him had he obtained the wanted connection over a direct route.

The first nine front contacts of route relays TKa/h are supplied three by three by the wires referenced ba/h , ca/h , da/h , terminating at input terminals of allotter RT referenced Eba/h , Eca/h , Eda/h .

It is quite obvious that the three 3-contact groups previously mentioned cannot be supplied simultaneously when a route relay pulls up, since each 3-contact group,

when supplied, furnishes the register the elements required for the routing of the wanted call over a special path. To meet this requirement a certain number of so-called category relays have been provided, referenced $TTa \dots TTf$, whose front contacts are so arranged that they make up 8 so-called discrimination pyramids, each having one input wire, capable of being grounded, and 3 outgoing wires, referenced $P1a, P1b, P1c \dots P8a, P8b, P8c$. These wires terminate at output terminals of incoming allotter RT referenced $11/8/a/c$. Wires $P1a \dots P8c$ are connected to the output terminals as follows:

- Wire $P1a$ is connected to terminal $I1a$
 Wire $P1b$ is connected to terminal $I1b$
 Wire $P8c$ is connected to terminal $I8c$

Thus a certain number of discrimination pyramids can be obtained thanks to these contact pyramids. Output terminals $11/8/a/c$ are used to supply the 3-contact groups of the above-mentioned route relays. Stated otherwise, when a subscriber of a given category asks for the establishment of a certain connection it suffices, in order to cause the energization of the six auxiliary relays charged with sending to the register the signals required for the establishment of said connection, to jumper one of output terminals $11/8/a/c$ to one of the input terminals Eba/h or Eca/h or Eda/h corresponding to a certain group of three front contacts of the route relay that has just pulled up.

To make these explanations specific, the discussion will be resumed of the translation of the code corresponding to the area call chosen as an example at the beginning of this description. It will be recalled that the code 828 has caused the pulling up of route relay TKe and further that this pulling up has required the translation of only the first 2 digits, that is, of digits 8 and 2. It is known that the signals sent by the translator to the register are characterized by the pulling up of certain ones of relays $EWa/e, EXa/e, EYa/e, EZa/e$. To be specific, 2 relays pull up in each of said four 5-relay groups. To simplify the description that follows, the 10 combinations it is possible to obtain by causing the simultaneous pulling up of 2 out of the 5 relays making up a given group are numbered 1 to 0. In addition, the 5-relay group involved will be denoted by having each digit comprised between 1 and 0 preceded by the letter characterizing the group involved. These letters are 4 in number, W, X, Y, Z , and they denote relay groups $Ewa/e \dots EZa/e$. The code used is the same already mentioned in connection with the registering relays. The following table gives the designation of the relays that pull up for a given combination index.

	W	X	Y	Z
1-----	EWa	EWe	EXa	EXe
2-----	EWb	EWc	EXb	EXe
3-----	EWa	EWb	EXa	EXb
4-----	EWc	EWe	EXc	EXe
5-----	EWa	EWa	EXa	EXc
6-----	EWb	EWc	EXb	EXc
7-----	EWc	EWd	EXd	EXe
8-----	EWd	EWe	EXd	EXe
9-----	EWa	EWd	EXa	EXd
0-----	EWb	EWd	EXb	EXd

Thus, in what follows, the use of the designation $W5$, for example, means that the translator has sent the register signals that cause in said register the pulling up of relays EWa, EWc .

To route a call whose number is 828-25-70, it will be assumed that the translator sends the register the following code signals: $W3, X1, Y8, Z3$.

To do so, the terminals of allotter RT shown below are connected two by two as follows:

- (1) Terminal $G51$ is connected to terminal $Hw3$;
 (2) Terminal $G52$ is connected to terminal $Hx1$;
 (3) Terminal $G53$ is connected to terminal $Hy8$;

- (4) Terminal $G60$ is connected to terminal $Hz3$;
 (5) Terminal $I2a$ is connected to terminal Ebe .

It will be recalled that the fact that the calling subscriber is a regular subscriber is characterized in the translator by the pulling up of relays Tb and Tf ; from this it follows that the energizing circuits of relays $TPa, TPb, TQa, TQe, TRd, TRe, TSa, TSb$ are completed upon the pulling up of route relay TKe :

- (1) Battery, middle winding of relay TPb , upper winding of relay TPa , wire $Wa3$ through cable W , jumper interconnecting terminals $Hw3$ and $G51$, wire $Twe1$ through cable T , front $TKe1$, wire be , jumper interconnecting terminals Ebe and $I2a$, wire $P2a$ through cable P , front $TTf3$ of category relay RRf , ground;

- (2) Battery, middle winding of relay TQa , upper winding of relay TQe , wire $Xa1$ through cable X , jumper interconnecting terminals $Hx1$ and $G52$, wire $Txe2$ through cable T , front $TKe2$, ground over a circuit previously described;

- (3) Battery, middle winding of relay TRe , upper winding of relay TRd , wire $Ya8$ through cable Y , jumper interconnecting terminals $Hy8$ and $G53$, wire $Tye3$ through cable T , front $TKe3$, ground over a circuit previously described;

- (4) Battery, middle winding of relay TSb , upper winding of relay TSa , wire $Za3$ through cable Z , jumper interconnecting terminals $Hz3$ and $G60$, wire $Tz10$ through cable T , front $TKe10$, ground.

The pulling up of the above-mentioned auxiliary relays causes the sending to the register of selective combinations allowing it to control the routing of the wanted connection. Through the closing of their front contacts $TPa1, TPb1, TQa1, TQe1, TRd1, TRe1, TSa1, TSb1$, said relays complete a holding circuit for relay TCk : battery, upper winding of relay TCk , wire $Ck1$, above-mentioned front contacts in parallel, ground.

Through the closing of their front contacts $TPa2, TPb2, TQa2, TQe2, TRd2, TRe2, TSa2, TSb2$, auxiliary relays $TPa, TPb, TQa, TQe, TRd, TRe, TSa, TSb$ complete energizing circuits for relays $EWa, EWb, EXa, EXe, EYd, EYe, EZa, EZb$:

- (1) Battery, relay EWa , wire Ewa through cable E and translator connector CT , front $TPa2$, ground;

- (2) Battery, relay EWb , wire Ewb through cable E and translator connector CT , front $TPb2$, ground;

- (3) Battery, relay EXa , wire Exa through cable E and translator connector CT , front $TQa2$, ground;

- (4) Battery, relay EXe , wire Exe through cable E and translator connector CT , front $TQe2$, ground;

- (5) Battery, relay EYd , wire Eyd through cable E and translator connector CT , front $TRd2$, ground;

- (6) Battery, relay EYe , wire Eye through cable E and translator connector CT , front $TRe2$, ground;

- (7) Battery, relay EZa , wire Eza through cable E and translator connector CT , front $TSa2$, ground;

- (8) Battery, relay EZb , wire Ezb through cable E and translator connector CT , front $TSb2$, ground.

The operation of relays EWa, EWb, EXa and EXe has already been discussed.

Through the closing of their front contacts $EYd1, EYe1, EZa1, EZb1$, relays EYd, EYe, EZa, EZb complete holding circuits for themselves over a common circuit already described.

It will be noted in Fig. 4 that two control pyramids, similar to those already described in connection with the control of relays EWa/e and EXa/e , have been provided to ensure the proper operation of relays $EYa/e, EZa/e$. All these pyramids are connected in series; stated otherwise, when the register receives from the translator the information required for the routing of an area call, relay EDp can pull up only after said pyramids have checked the proper operation of the above-mentioned code-receiving relays.

The other contacts of relays EYd and EYe , that is, the contacts other than those providing the holding of

these relays and those controlling the control pyramid (EYd2, EYd3, EYe2), are inoperative at this time.

Over their front contacts EZa2, EZb2, relays EZa and EZb prepare the circuit used for sending the toll chargeable to the calling subscriber. The other contacts of these relays control the corresponding control pyramid.

If the control of relays EWa, EWb, EXa, EXe, EYd, EYe, EZa, EZb is favorable, relay EDp pulls up and causes the starting of the group-selecting operations in accordance with a method identical with the one described in connection with the discussion of the routing of a local call. It will be noted however that back contact EDp4 is now used to break the energizing circuit of translator-seizure relay EJq.

The release of the translator is effected under the control of relay TCk, which remains pulled up so long as one of the relays of said translator remains pulled up. The release is effected as from translator connector CT, which breaks the connection between the register and the translator, this entailing the release of relay TEk and the release of the decoding relays. The release of said decoding relays entails the release of the route relay and of the code-sending auxiliary relays. Finally, relays TCk, TTb, TTf release in turn; the translator is released and can be connected again to some other register.

In spite of the release of the translator, the code-receiving relays EWa/e, EXa/e, EYa/e, EZa/e that pulled up hold over circuits already described.

Relay EDm pulls up at the end of the group-selecting operations. Owing to the non-energization of relay EFf (area call), the closing of back contact EDm2 completes the energizing circuit of relay REp, which pulls up: battery, relay REp, wire Ri through cable R, back EFf1, Efk1, front EFe1, EDp2, back EDm2, EFc4, ground on general holding wire tg.

Through the opening of its back contact REp1, relay REp restores the timing device to normal. Through the closing of its front contact REp2 (Fig. 7), relay ECl is short-circuited. Front contact REp3 applies battery to wire Ab2 to cause the seizure of an outgoing connector at the exchange involved; wire Ab2, front CEc7, wire Bb2 through cable B, back REq7, front REp3, resistance RR4, battery.

Pulsing motor RM is started by the closing of front contact REp4. Relay REp complete a holding circuit for itself through the closing of its front contact REp5: battery, relay REp, front REp5, wire Rg through cable R, back EFc4, ground on general holding wire tg.

The energizing circuit of relays EDm and EFa is prepared by the closing of front contact REp6. Finally, a ground is applied to wire Iq to fault register ED by the closing of front contact REp7.

As can be noted, the register prepares the sending of outgoing dialing pulses even before having received all the digits making up the called subscriber's number. This arrangement allows saving time in the establishment of an area connection. Since the sending of information from the register at the originating exchange to the register at the terminating exchange is done in the form of numerical pulses, it follows that considerable time is saved by starting to send the pulses to the distant exchange before having received the called subscriber's full number.

When the distant equipment is ready to receive the dialing pulses sent from the register of the originating exchange, it so tells the register of said originating exchange by sending battery over wire Aa2, the effect of this being to cause the pulling up of relay EDm: ground, front REp2, right-hand winding of relay EDm, rectifier EQ3, wire Re through cable R, front REp6, wire Fa2, back REq6, RDp1, wire Ba2 through cable B, front CEc8, wire Aa2 connected to battery.

The pulling up of relay EDm causes the starting of the pulse sender. The closing of front contact EDm3 completes the energizing circuit of relay REq, which pulls up: battery, relay REq, front EDm3, REp5, wire Rg

through cable R, back EFc4, ground on general holding wire tg.

The pulse sender is controlled by relay REq.

The pulling up of relay REq prepares, through the switching into operating position of make-break contact REq1, the energizing circuit of relay RBg and the opening of the energizing circuit of relay RDab. Slow-releasing relay RDab remains operated for a moment. The closing of front contact REq2 completes the energizing circuit of relay EKc, which pulls up: battery, relay EKc, back Elk2, Elh2, Ele2, Elb2, Ekp2, Ekm2, Ekl2, Ekg2, Ekd1, wire Rk through cable R, front REq2, back RDd2, ground on wire Db over a circuit already described.

The closing of front contact REq3 causes the starting of the timing device, which operates identically as already described. The energizing circuit of pulse-repeating relay RBf is prepared by the closing of contact REq4. Relay REq completes a holding circuit for itself through the closing of its front contact REq5: battery, relay REq, front REq5, then ground over a circuit already described.

Wires Aa2 and Ab2 are looped to beating contact RBf3 by the switching into operating position of make-break contacts REq6 and REq7, while relay EDm releases, its energizing circuit having just been broken by the opening of back contact REq6.

The release of relay EDm has no effect at this time. Relay EKc completes a holding circuit for itself through the closing of its front contact EKc1: battery, relay EKc, wire Ro through cable R, front RKc1, back RDd1, ground over a circuit already described.

Relay RDab releases after a moment. Through the switching into normal position of its make-break contact RDb1, it removes the short-circuit from relay RBg and completes its energizing circuit: battery, resistance RR3, relay RBg, back RBg4, RBf2, RBn5, RDc1, RDb1, front REq1, wire Db across Figs. 3 and 4, front RAc1, ground.

The closing of back contact RDb2 prepares the energizing circuit of repeating relay RBf.

Relay RBg completes a holding circuit for itself through the closing of its front contact RBg1: battery, resistance RR3, relay RBg, front RBg1, REq1, ground over a circuit already described.

The closing of front contact RBg2 prepares the circuit used for sending pulses to pulse counter NV. The energizing circuit of relay RBn is prepared by the closing of front contact RBg3. The opening of back contact RBg5 removes the short-circuit from beating relay RBf3.

Pulsing motor RM drives a cam RK3 that periodically opens and closes the circuit it controls.

To fix ideas it will be assumed that cam RK3 is in opening position when motor RM starts. At the end of a certain period of time, this cam closes the circuit of pulse-repeating relay RBf, which pulls up: battery, relay RBf, back RBn6, RDb2, front REq4, cam RK3 in closing position, ground.

Through the closing of front contact RBf2 a pulse is sent to pulse counter NV over wire Nvc: pulse counter NV, wire Nvc, front RBg2, RBf2, back RBn5, RDc1, RDb1, ground over a circuit already described.

The opening of back contact RBf3 removes the looping of wires Aa2 and Ab2, thus marking the beginning of the first dialing pulse.

It was assumed before, for simplification, that pulsing cam RK3 was in opening position when pulsing motor RM started. It is quite obvious that cam RK3 can be in any position when motor RM starts and particularly that it can be in closing position. In this case, relay RBg cannot pull up, its energizing circuit being short-circuited by the switching into operating position of its make-break contact RBf2. When, owing to its rotation, cam RK3 opens the energizing circuit of relay RBf, the energizing circuit of relay RBg is completed by the switching into normal position of make-break contact RBf2. Things are thus back to the preceding case. This

arrangement thus prevents the energization of relay RBg when cam RK3 is in closing position at the time of the release of relay RDab.

As has been pointed out before, the register must, depending upon the case, send the terminating exchange either part or all of the digits making up the called subscriber's number. This signal is furnished it by the translator and it is characterized by the pulling up of two of relays EYa/e. A table included hereinbefore lists the relays that pull up for each value of Y. The various values that Y can take correspond to the various quantities of the telephone number's digits that must be sent by the register to the distant exchange. Throughout what follows it will be taken that the quantity of digits in a given telephone number that must be sent by the register is equal to the value of the figure accompanying the letter Y in the above-mentioned table less one unit. Thus, in the example chosen, the value of Y8 means that the register must send the distant exchange 7 digits of the called subscriber's number; since the number for an area call comprises 7 digits, it follows that in this case the distant exchange is sent the full number dialed by the calling subscriber.

The arrangement for sending the pulses to the distant exchange is as follows. There are five scanning relays RBa . . . RBe (Fig. 3) capable of "duplicating" registering relays EOz/e, EPa/e . . . EUa/e. To do so, the registering relays can provide the control for said scanning relays over their front contacts EOa2/e2 . . . EUa2/e2 (Figs. 4, 5 and 6). These contacts through their operation ground wires Eaa/e, Eba/e . . . Ega/e. The grounding of wires Eaa/e, Eba/e, Eca/e is done over the following circuits (Fig. 6):

- (1) Wires Eaa/e through cable E, front EOa2/e2, back Elq1, ground;
- (2) Wires Eba/e through cable E, front EPa2/e2, back Elq1, ground;
- (3) Wires Eca/e through cable E, front EQa2/e2, back Elq1, ground.

The grounding of wires Eda/e, Eea/e, Efa/e has already been described before with reference to local calls.

The grounding of wires Ega/e is obvious in Fig. 5.

A control wire Ra . . . Re is associated with each scanning relay RBa . . . RBe. The five control wires Ra . . . Re of the five scanning relays RBa . . . RBe can be connected in succession to the corresponding wires of wire groups Eaa/e . . . Ega/e through a chain of directing contacts EKf1/5, EKf1/5, EKf1/5, EKf1/5, ELa1/5, ELd1/5.

The pulses sent out by cam RK3 are counted by a counter NV similar to the one referenced NR and previously discussed. This counter comprises 6 counting relays referenced RBh . . . RBm, whose energizing windings, located within rectangle NR, are not shown. Certain of these counting relays pull up, depending upon the number of pulses sent out by cam RK3 following the pulling up of relay RBg. The following table gives the designation of the relays that pull up after counter NV has received a given number of pulses.

	RBh	RBl	RBj	RBk	RBl	RBm
1.	T	T	T	R	R	R
2.	R	R	T	T	R	R
3.	T	T	R	T	R	R
4.	R	R	R	R	T	R
5.	T	T	T	R	T	R
6.	R	R	T	T	T	R
7.	T	T	T	T	T	T
8.	R	R	R	R	R	T
9.	T	T	T	R	R	T
10.	R	R	T	T	R	T

In this table, the letters T denote the relays operated and the letters R the relays unoperated.

In order to control the sending of the numerical pulses corresponding to any digit of the number, a pyramid

has been provided consisting of a certain number of contacts belonging to scanning relays RBa . . . RBe and to counting relays RBh . . . RBm. When unoperated, the pyramid is designed not to provide any metallic continuity in the energizing circuit of relay RBn. In proceeding to send the numerical pulses corresponding to a predetermined digit of the number, the control wires of the scanning relays are connected through the aforementioned directing contacts to the corresponding front contacts of the registering relays for the digit involved. From this it follows that 2 scanning relays pull up and through the closing of their front contacts in the aforementioned contact pyramid prepare the energizing circuit of relay RBn. When the last pulse of the pulse train corresponding to the number's digit involved has been sent to the distant exchange, the counting relays that then pull up complete through the closing of their front contacts in the contact pyramid the energizing circuit of relay RBn, which pulls up and causes the stopping of the pulse sender.

Directing contacts EKf1/5, EKf1/5, EKf1/5, EKf1/5, ELa1/5, ELd1/5 belong to relays arranged in a chain, as examination of the right-hand portion of the figure will show.

That relay chain operates in a classical manner, that is, it advances one step following the sending of a pulse train, the direction of advance being such that the relays making it up pull up in the order EKf1/5 . . . ELd1/5. Since the number of digits to be sent depends essentially on the destination of the wanted connection, it follows that the operation of the chain of directing relays does not necessarily commence with the energization of relay EKf1/5 after the sending of the first pulse train corresponding to the digit P (case where Y=8, 7 digits to be sent). In order to ensure the sending of a predetermined number of digits, the directing relay is energized before any digit sending, this connecting the scanning relays to the registering relays corresponding to the first digit to be sent. The control of the directing relays is provided by relays EYa/e, a certain number of auxiliary contacts of which have been provided. Depending upon the Y value sent by the translator to the register, such or such directing relay pulls up upon the energization of the two relays EY corresponding to the Y value, this entailing the starting of the chain of directing relays as from the directing relay that has just pulled up.

Along the same order of ideas, provision has been made for the sending of toll pulses. To do so, the scanning relays can "duplicate" relays EZa/e. To that end a directing relay ELjk has been provided that through the action of its directing contact ELj1/5 can connect the control wires Ra . . . Re of scanning relays RBa . . . RBe to front contacts EZa2 . . . EZa2 of toll relays EZa . . . EZa.

To make these explanations specific, the discussion will be resumed of the sending of the digits making up the called subscriber's number.

Since the register has received from the translator the signal Y8, all the digits making up the number, that is, 7 digits, must be sent to the distant exchange. To meet this requirement, relays EYd, EYe, which have just pulled up, do not cause the energization of any of the directing relays. From this it follows that scanning relays RBa . . . RBe are placed under the control of the relays EOa/e registering the first digit of the called subscriber's number, that is, digit P. It will be recalled that in the example chosen P=8, this corresponding to the energization of registering relays EOa, EOe and of scanning relays RBd, RBe over circuits already described.

Through the closing of their front contacts RBd4, RBd3, the scanning relays prepare the energizing circuit of relay RBn. Front contacts RBd1, RBd2, RBd5, RBd1, RBd2 form part of a contact pyramid providing the control of the scanning relays. This pyramid is so designed that it provides the metallic continuity of the energizing

winding of relay RD1 when the number of scanning relays pulled up is other than 2.

At the end of the first pulse cam RK3 breaks the energizing circuit of relay RBf, which releases. The switching into normal of make-break contact RBf2 causes the sending of a ground to counter NV over control wire NVa; wire NVa, back RBf2, ground over a circuit already described.

The closing of back contact RBf3 entails the looping of wires Aa2 and Ab2.

After a moment, cam RK3 again completes the energizing circuit of relay RBf, which pulls up, thus causing the sending of a new pulse. The previously-described operations thus recur in identical fashion up to the end of the eighth pulse.

At that instant, relay RBf releases as before, while in pulse counter NV relay RBn is pulled up, as can be seen from the above-mentioned table. The energizing circuit of relay RBn is then completed and this relay pulls up: battery, relay RBn, back RBf2, front RBm3, RDd4, RBe3, back RBf1, front RBg3, ground over a circuit already described.

The pulling up of relay RBn causes the stopping of the pulse sending to the distant exchange and the advancing by one unit of the chain of directing relays.

The opening of back contact RBn1 entails the restoration to normal of the above-described timing device. The holding circuit of relay RBn is completed by the closing of front contact RBn2: battery, relay RBn, front RBn2, ground over a circuit already described.

A ground is applied to wire Ip to fault register ED through the closing of front contact RBn3. The closing of front contact RBn4 completes the energizing circuit of relay RDcd, which pulls up: battery, relay RDcd, front RBn4, ground on wire Db.

The opening of back contact RBn5 prepares the release of the relays of pulse counter NV. The opening of back contact RBn6 prevents relay RBf from bearing at the rate of cam RK3.

The energization of relay RDcd entails that of relay RDab through the closing of make-break contact RDd1: battery, relay RDab, front RAc5 and RDd1, ground on wire Db over a known circuit.

The opening of the two back contacts RDd1 and RDd2 breaks the energizing circuit of relay EKc, which releases. The closing of front contact RDd2 completes the energizing circuit of relay EKd, which pulls up: battery, relay EKd, back EKg3, EKj3, EKm3, EKp3, ELb3, ELE3, ELh3, ELk3, wire Rn through cable R, front RDd2, ground on wire Db.

The energization of relay RDab causes the release of relay RBg owing to the short-circuiting of the energizing winding of said relay by the closing of front contact RDb1.

The energization of relay EKd prepares the energization of directing relay EKfg through the closing of front contact EKd1. A ground is applied to wire Id to fault register ED by the closing of front EKd2.

The release of relay RBg entails the release of relay RBn and of the counting relays of counter NV through the opening of its front RBg3.

In turn, the release of relay RBn breaks through the opening of its front contact RBn4 the energizing circuit of relay RDcd. This slow-releasing relay homes after a moment. The closing of make-break contact RDd2 completes the energizing circuit of directing relay EKfg, which pulls up, while relay EKd holds in series with said relay EKfg: battery, relay EKd, left-hand winding of relay EKfg, front EKd1, wire Rk through cable R, front REq2, back RDd2, ground on wire Db.

Further, the opening of front contact RDd1 breaks the energizing circuit of relay RDab, which releases with a certain delay.

The energization of directing relay EKfg causes the connection of scanning relays RBa . . . RBe to the front

contacts of the relays (EPa . . . EPe) registering the number's second digit, namely, digit Q. Over its front contact EKg2, relay EKfg prepares the energizing circuit of relay EKij. Front contact EKg3 prepares through its closing the holding circuit of relay EKfg.

Relay RDab releases after a moment, thus marking the beginning of the sending of the second digit's pulses. The above-described operations then recur in identical fashion. At the end of the sending of the second pulse-train, relay RDcd pulls up and completes the holding circuit of relay EKfg: battery, right-hand winding of relay EKfg, front EKg3, back EKj3, EKm3, EKp3, ELb3, ELE3, ELh3, ELk3, wire Rn through cable R, front RDd2, ground on wire Db.

Further, the opening of back contact RDd2 breaks the holding circuit of relay EKd, which releases and through the closing of its back contact EKd1 prepares the energizing circuit of relay EKij.

When relay RDcd homes, it completes the energizing circuit of relay EKij, which energizes, while relay EKg holds in series with said relay EKij: battery, right-hand winding of relay EKfg, right-hand winding of relay EKij, front EKg2, back EKd1, wire Rk through cable R, front REq2, back RDd2, ground on wire Db.

The pulse sending will thus continue up to the end of the last pulse-train, corresponding to units digit 0. At that instant, relays ELde and ELab are pulled up, while relay RDcd pulls up after the sending of the tenth pulse.

The switching into operating position of make-break contact RDd2 then completes the holding circuit of relay ELde and opens the energizing circuit of relay ELab, which releases and through the closing of its back contact ELb2 completes the energizing circuit of relays ELgh and ELjk.

Upon homing, relay RDcd completes, through the restoration to normal of its make-break contact RDd2, the energizing circuit of relays ELgh and ELjk, which pull up:

(1) Battery, left-hand windings in series of relays ELde and ELgh, front ELE2, ground over a circuit already described;

(2) Battery, right-hand windings in series of relays ELgh and ELjk, back EEo6, ground over a circuit already described.

The pulling up of directing relay ELjk places scanning relays RBa . . . RBe under the control of toll-code sending relays EZa . . . EZe.

The closing of front contacts ELk2, ELk3, prepares the energizing circuit of relay RAp. The toll-pulse sending circuit is prepared by the closing of front contact ELk4. Front contact ELk5 short-circuits wires Aa2 and Ab2.

The sending of the metering pulses is done by beating-contact RBf1 over wire Ac2: wire Ac2, front CEc5, wire Bc2 over cable B, back RAp1, front ELk4, beating contact RBf1, ground over a circuit already described.

Beating contact RBf3, being short-circuited by front contact ELk5, is inoperative.

When the metering-pulse train is sent, relay RDcd pulls up and through the switching into operating position of its make-break contact RDd2 completes the holding circuit of relay ELjk: battery, left-hand winding of ELjk, front ELk3, wire Rn through cable R, front RDd2, ground on wire Db.

Directing relays ELgh and ELde, having their energizing circuit broken by the opening of back contact RDd2, release.

After a moment, relay RDcd releases again as known and completes the energizing circuit of relay RAp, which pulls up: battery, left-hand winding of ELjk, wire Rm through cable R, upper winding of RAp, wire Rl through cable R, front ELk2, ground over a circuit already described.

The pulling up of relay RAp entails the release of the register exactly as described with reference to a local

call. It will be noted however that a contact $RAp1$ is provided that disconnects wire $Bc2$ in order to prevent the sending of additional metering pulses over this wire in case beating contact $RBf1$ is still switched in because the register is slow in releasing.

The establishment will now be described of an area connection requiring translation of the first three digits making up the called subscriber's number. It will be assumed by way of example that the called subscriber's number is 272-25-70.

The seizure of the register and the translator is effected like before and requires no further description.

The decoding in the translator of the number's first two digits, namely, digits 2 and 7, causes by known means the grounding of wire $Kb27$ and of the corresponding output terminal (B27).

Since the code 272 calls for the translation of three digits, output terminal B27 cannot therefore be connected to the energizing winding of a route relay (through a jumper connecting output terminal B27 to the input terminal associated with a given route-relay).

To ensure the translation of 3 digits a certain number of third-digit relays have been provided, referenced TFa/j in Fig. 8 and controlled by outgoing wires referenced $La1/10$ in third-digit decoding pyramid D3C.

These relays' front contacts, referenced $TFa/j/2/11$, terminate at input terminals referenced $Ca/j/2/11$ and at output terminals $Da/j/2/11$.

When the translator must receive codes requiring the translation of three digits, certain of the output terminals $B10/99$, corresponding to the decoding of the first two digits, are jumpered to certain of the input terminals $Ca/j/2/11$ and certain of the output terminals $Da/j/2/11$ are jumpered to certain of the input terminals Ea/h .

It follows from the foregoing explanations that the reception by the translator of code 272 causes the pulling up of third-digit relay TFb : battery, TFb , wire $La2$, ground through third-digit decoding pyramid D3C.

The following terminals are jumpered together in allotter RT:

Output terminal B27 jumpered to input terminal $Cb2$;
Output terminal $Db2$ jumpered to input terminal Ee .

It follows therefore that route relay TKe pulls up: battery, relay TKe , terminals Ee and $Db2$ jumpered together, front $TFb2$, terminals $Cb2$ and $B27$ jumpered together, ground over a circuit already described.

Route relay TKe therefore pulls up as in the case of the first area call described (telephone number 828-25-70).

The following operations required for the establishment of the connection are performed as in the case of the area call already described.

It will be noted that route relay TKe pulls up in both area-call examples described above; this case can arise for example when the wanted connections terminate at two different exchanges located in one and the same city.

The case will now be described of an area call requiring translation of 3 digits for the routing of the call and translation of 4 digits for determination of the tolls. It will be assumed that the number 931-25-70 meets this requirement.

The reception of the code 931 brings about in the translator the grounding of output terminal $B93$. This terminal is jumpered in allotter RT to the input terminal $Ca2$ corresponding to the second front-contact of third-digit relay TFa , which has just pulled up (third digit 1 of number 931-25-70). The corresponding output terminal $Da2$ is jumpered in allotter RT to the input terminal Eh corresponding to route relay TKh . It will be noted that the operation of the translator is identical up to this point with the one described with reference to the establishment of an area connection requiring the translation of three digits.

The pulling up of route relay TKh allows furnishing the register the information required to control the estab-

lishment of the connection. In the example chosen this information is: $W=3$, $X=2$, $Y=5$.

To send this information to the register, the auxiliary relays involved in sending the code W, X and Y are controlled as before by the first three front contacts ($TKh1$, $TKh2$, $TKh3$) of route relay TKh . These three contacts are supplied from outgoing wire $P2b$ of the above-mentioned pyramid of discrimination contacts. To do so, the output terminal $I2b$ associated with wire $P2b$ is jumpered in allotter RT to the input terminal Ebh associated with the first three front contacts ($TKh1$ . . . $TKh3$) of relay TKh .

It will be noted that the value of Z is not included in the information sent from the translator to the register. This is due to the fact that 3 digits cannot suffice to determine the tolls to be charged the calling subscriber. To characterize this condition, output terminal $G80$ (corresponding to front contact $TKh10$ of route relay TKh) is jumpered to input terminal Is in allotter RT.

The grounding of terminals Is will be used to tell the register that the translator needs a fourth digit to enable it to determine all the information required for the establishment of the wanted connection. The grounding of terminal Is causes in the register the pulling up of relay $EDq4$ (Fig. 4): battery, relay EBo , relay EDq , wire Eg through cable E and translator connector CT, resistance $TR15$, terminal Is jumpered to terminal $G80$ in allotter RT, wire $Tzh10$, front $TKh10$, ground.

Owing to the presence of resistance $TR15$ in the energizing circuit of relays EBo and EDq , only relay EDq pulls up, relay EBo , being a marginal relay, remaining unoperated.

The pulling up of relay EDq tells the register that the translator needs a fourth digit in order to be able to furnish it the full information required for the routing of the call.

In the present case, the register has received from the translator only the information concerning the values of W, X and Y. It will be recalled that these values are:

40 $W=3$, $X=2$, $Y=5$.

Reference to a previously-mentioned table will show that these values bring about in the register the energization of code relays EWa , EWb , EXb , EXe , EYa , EYc . These relays complete holding circuits for themselves over circuits already described.

45 It will be noted that relay EDp cannot pull up unless 2 relays are pulled up in each of the relays groups EWa/e , EXa/e , EYa/e , EZa/e . Consequently, in spite of the translator's sending the register the signals W, X and Y, relative to the routing of the call, relay EDp remains unoperated and accordingly the group-selecting operations cannot commence. Relay EDq completes a holding circuit for itself through the closing of its front contact $EDq1$: battery, relay EBo , relay EDq , front $EDq1$, resistance $ER8$, ground on general holding wire tg .

50 The switching into operating position of make-break contact $EDq2$ directs the energizing circuit of relay EJq to front contact $EGm1$, which controls the registering of the fourth digit of the called subscriber's number. 55 Since the translation time is short, it follows that relay EJq releases during the operation of make-break contact $EDq2$, because the register has not yet received the fourth digit at that instant. The translator is released in accordance with a method already described. The registers' code relays EWa , EWb , EXb , EXe , EYa , EYc remain pulled up.

60 Once the calling subscriber has dialed the fourth digit of the called subscriber's number and that digit has been registered by the corresponding relays, relay $EGm1$ pulls up as is known and then completes through the closing of its front contact $EGm1$ the energizing circuit of relay EJq , which again pulls up: battery, relay EJq , back $EF11$, $EDp4$, front $EDq2$, back $EBo2$, front $EGm1$, ground over a circuit already described.

65 The translator is again brought in by the pulling up

of relay EJq . It should further be noted that this translator can be different from the one seized the first time by the register. The operation of this translator is identical with that previously described. It will be recalled that route relay TKh pulls up and again sends the register the information required for routing the call, excluding the tolls: $W=3$, $X=2$, $Y=5$.

Since the translation of four digits is needed in order to determine the tolls to be charged to the calling subscriber and the translation of the first three digits is characterized by the pulling up of route relay TKh , secondary toll-relays, associated with the regular route-relays, are provided in order to simplify the equipment and to give the translator greater flexibility. These toll relays, referenced TNb/j in Fig. 8, have their energizing winding connected to terminals Nb/j of allotter RT. The number of toll relays shown in the figure is given as an example and it can vary in accordance with the requirements of the exchange for which the equipment may be intended. Contacts $TNb/j/1/10$ of these relays are connected to the 10 outgoing wires $Ma1/10$ issuing from fourth-digit decoding pyramid D4C. These 10 wires are multiplied to said contacts as follows:

Wire $Ma1$ multiplied to contacts $TNb1/j1$.

Wire $Ma10$ multiplied to contacts $TNb10/j10$.

The outgoing wires corresponding to these contacts terminate at output terminals $Fb/j/1/10$ of allotter RT. The connections are as follows:

Contact $TNb1$ connected to terminal $Fb1$.
Contact $TNb2$ connected to terminal $Fb2$.

Contact $TNb10$ connected to terminal $Fb10$.

Contact $TNb/j10$ connected to terminal $Fj10$.

The output terminals associated with said contacts are used to control auxiliary toll-code sending relays Tsa/e . To be precise, the putting through of an area call whose number is 931-25-70 will be described to the end. Route relay TKh is associated with secondary toll-relay TNe . This amounts to saying that terminals Eh and Ne are jumpered together in allotter RT, thus connecting in parallel the energizing windings of relays TKh and TNe . Output terminal $Fe2$ and terminal $Hz2$ are also jumpered together in allotter RT. It will be recalled that terminal $Fe2$ belongs to the second contact of the secondary route relay TFe associated with the main route relay TKh . The jumpering of terminals $Fe2$ and $Hz2$ means that following translation of the number's fourth digit, namely, digit 2, the secondary route relay determines the tolls to be charged, which is therefore $Z=2$ in the example chosen. Reference to a table mentioned before will show that the toll $Z=2$ calls for the energization in the register of code relays EZb and EZe or, what amounts to the same thing, the energization in the translator of auxiliary relays TSb and TSe . The energizing circuit of these relays is in effect completed by the pulling up of the auxiliary route relay as follows: battery, middle winding of relay TSb , lower winding of relay TSe , wire $Za2$ through cable Z , jumper between terminals $Hz2$ and $Fe2$, front $TNe2$, wire $Ma2$ grounded through fourth-digit decoding contact pyramid D4C.

It will be recalled that the main route relay furnishes on its own to the register the elements W , X and Y . Consequently, following the energization of secondary route relay TNe , the register is in possession of all the elements required for the routing of call 931-25-70 and accordingly relay EDp pulls up and controls the starting of the group selection. The routing of the call is thereupon effected like before.

Along the same order of ideas, the operation of the translator will be described for the case where the number dialed requires the translation of 4 digits for determination of the route and of the tolls. It will be assumed

as an example that number 456-25-70 meets this requirement.

It will be recalled that when the number requires the translation of four digits for the determination of the tolls, while the translation of three digits suffices for the determination of the route, the corresponding route relay pulls up, sends the register the signals relative to W , X and Y and controls the grounding of wire Eg across a resistance. The sending of the signals relative to W , X and Y is inoperative, since Z cannot be determined. When the register brings in the translator again after having registered the fourth digit, the same route relay pulls up again and sends the register the signals relative to W , X and Y , while the secondary toll-relay associated with the main route relay, being this time informed of the number's fourth digit, sends the register the signals relative to Z .

When four digits must be translated to determine the route and the tolls, it is imperative to apply a high ground to wire Eg without the help of a route relay, considering that the elements required for establishing said route are not known as yet. To do so, it suffices to jumper one of output terminals $Da/j/2/11$ to terminal Is in allotter RT.

To be precise, when the register is connected to the translator, a ground is applied to output terminal $B45$ upon the registering of the number's first three digits (456) and third-digit relay TFc pulls up. The following jumpers are provided in allotter RT:

(1) Output terminal $B45$ connected to input terminal $Cc2$;

(2) Output terminal $Dc2$ connected to terminal Is .

The grounding of terminal Is signals the register as is known that it must release the translator and then bring it in again once it has registered the fourth digit of the called subscriber's number, that is, digit 2 in the example chosen.

When the register brings the translator in again after having registered the fourth digit, fourth-digit relay Tib pulls up. It will be noted that the ten fourth-digit relays are wired the same way as described with reference to third-digit relays TFa/j .

Two jumpers are provided in allotter RT:

(1) A jumper connecting output terminal $Dc2$ to input terminal $Jb2$;

(2) A jumper connecting output terminal $Kb2$ to input terminal Eg .

Consequently, the energizing circuit of route relay TEg is completed and this relay pulls up: battery, relay TEg , terminal Eg , jumper connecting terminals Eg and $Kb2$, front $Tib2$, terminal $Jb2$, jumper between terminals $Jb2$ and $Dc2$, front $TFc2$, terminal $Cc2$, jumper between terminals $Cc2$ and $B45$, ground over a circuit already described.

The pulling up of route relay TKg allows furnishing the register the information needed to route the call in accordance with a known method.

The same principle is used where 5 digits must be translated to determine the information required for the routing of the call.

First the number's first three digits are translated in accordance with a known method upon the seizure of the translator, this grounding terminal Is , thereby telling the register that it must send a fourth digit. The translator thereupon releases.

When the register has received the fourth digit, it brings the translator in again and sends it the number's first four digits, a ground is applied to terminal It to wire Eg and an auxiliary route relay not shown pulls up. To do so, one of terminals $Ka/j/2/11$ is jumpered to terminal It without energizing a route relay. This time, wire Eg is connected to free ground, the effect of this being to cause the pulling up of marginal relay EBo of the register (Fig. 6). By its pulling up, this relay tells the register that the translator must know the number's fifth digit in order to send the register the information needed for the routing of the call.

By closing its front contact **EB₀₁**, relay **EB₀** completes a holding circuit for itself by short-circuiting resistance **ER₈**. Make-break contact **ED₀₂** directs the energizing circuit of translator-seizing relay **EJ_q** to contact **EG_{p1}** of fifth-digit receiving control relay **EG_{op}**.

Consequently, relay **EJ_q** falls back and releases the translator. When the register has received the number's fifth digit, it brings a translator in for the third time and sends it the number's first five digits. A fifth-digit relay pulls up. This relay is not shown but it is connected the same way as described with reference to third-digit relays **TF_{a/j}**. In combination with the above-mentioned auxiliary route relay, it completes the energizing circuit of a route relay, which thereupon sends the register the information required for the routing of the call.

Up to here it has been assumed that the calling and the called subscribers were regular subscribers and that the connection had been established by direct lines, that is, without rerouting. A few special cases will now be examined and the operation of the register and of the translator will be described for each of them.

First the case will be considered of a call that requires rerouting. To fix ideas, let the called subscriber's number be 931-25-70. The putting through of a call to that number has already been discussed, but using a direct path. To consider the case of putting the call through with rerouting, the description will be resumed of the routing of the call over a normal path up to the end of the group-selecting operations. It is well to explain that when the calling subscriber removes his handset and dials 931-25-70, he is automatically connected to the called subscriber over a direct path. Rerouting is needed only if all the direct lines over which the called party can be reached are busy. For the register and primarily the translator to be informed that all the direct lines that can be used for the routing of a particular call are busy, it is necessary first to start the group-selecting operations giving access to the normal paths, to check that said paths are busy and then to bring about the group-selecting operations giving access to the rerouting paths.

Hence it will be assumed that at the end of the group-selecting operations involved in routing a call to number 931-25-70 all the normal paths are found to be busy. A positive to ground polarity is then applied to wire **Fe** by the marker seized by the group-selection receiver connected to the register. That polarity causes the pulling up of relay **EF_a** through rectifier **EQ₄**: ground, relay **EF_a**, rectifier **EQ₄**, wire **Re**, front **EB_{q2}**, wire **Fe** to the group-selection marker through receiver connector **CR**.

The pulling up of relay **EF_a** completes through the closing of its front contact **EF_{a1}** the energizing circuit of relay **EF_c**, which pulls up: battery, left-hand winding of relay **EF_c**, back **EF_{b2}**, front **EF_{a1}**, ground on general holding wire **tg**.

A ground is applied to wire **Iw** toward fault register **ED** by the closing of front contact **EF_{a2}**.

The pulling up of relay **EF_c** will cause the release of all the relays engaged in controlling of group-selecting operations. Relay **EF_c** completes a holding circuit for itself through the closing of its front contact **EF_{c1}**: battery, left-hand winding of relay **EF_c**, front **EF_{c1}**, back **EF_{b5}**, ground on wire **tg**.

The closing of front contact **EF_{c3}** prepares the energizing circuit of relay **EF_b**. The opening of back contact **EF_{c4}** causes the removal of the ground from wire **Rg**, this entailing the release of relay **EF_{jk}**. The opening of back contact **EF_{c6}** breaks the holding circuit of relays **EW_{a/e}**, **EX_{a/e}**, **EY_{a/e}**, **EZ_{a/e}**, thus entailing the release of those that had pulled up following the reception of the information sent by the translator.

The release of code-sending relays **EW_{a/e}** . . . **EZ_{a/e}** entails the release of relay **ED_p**. The receiver connector, the receiver and the marker seized release in accordance with the usual methods.

The release of the relays seized for the group selection,

including the release of relay **EF_a**, is controlled by relay **EF_b**. When this release becomes effective, relay **EF_b** pulls up: battery, relay **EF_b**, back **ED_{m4}**, front **EF_{c3}**, back **EF_{d4}**, **EF_{e4}**, **ED_{n1}**, **ED_{p3}**, **EF_{a1}**, ground on wire **tg**.

5 The energization of relay **EF_b** will cause the re-seizure of a translator and the sending of a rerouting signal to said translator.

Through its front contact **EF_{b1}**, relay **EF_b** completes a holding circuit for itself over general grounding wire **tg**.
10 The energizing circuit of relay **RC_f** is prepared by the closing of front contacts **EF_{b2}** and **EF_{b3}**. The closing of front contact **EF_{b4}** prepares the circuit that sends the translator a signal telling it that there is rerouting. Relay **EF_c** has a holding circuit opened by back contact **EF_{b5}**.

15 The release of relay **EF_c** completes the energizing circuit of translator-seizing relay **EJ_q** through the closing of its back contact **EF_{c4}**: battery, relay **EJ_q**, back **EF_{f11}**, **ED_{p4}**, **ED_{q2}**, **EE₀₁**, **EEM₃**, front **EG_{j1}**, wire **Rg** across Figs. 4, 5 and 6, back **EF_{c4}**, ground on wire **tg**.

20 The translator is called in in accordance with the usual methods. The same route relay (**TK_h**) pulls up, while the ground applied to wire **Ei** in the register by front contact **EF_{b4}** completes the energizing circuit of rerouting-discrimination relay **TT_a**, which pulls up: battery, relay **TT_a**, wire **Ei** through cable **E** and translator connector **CT**, front **EF_{b4}**, ground.

25 The pulling up of relay **TT_a** tells the translator that the register requires a rerouting. Through the opening of its back contact **TT_{a1}**, it prevents the energization of relay **TT_b** upon the seizure of the translator. Through the closing of its front contact **TT_{a2}**, relay **TT_a** completes a holding circuit for relay **TK_k** in accordance with a known method. The closing of front contacts **TT_{a3}** . . . **TT_{a10}** causes the grounding of discrimination wires **P_{1c}** . . .

35 **P_{8c}**. It will be recalled that during the first seizure of the translator for establishing the present connection without rerouting route relay **TK_h** furnished the auxiliary code-sending relays the signals relative to **W**, **X** and **Y** through

40 the action of its three front contacts **TK_{h1}**, **TK_{h2}** and **TK_{h3}**, supplied by suitable jumpers from discriminating wire **P_{2b}**.

In the present instance, that is, with rerouting of the call, wire **P_{2b}** is disconnected, due to the fact that relay **TT_b** stays unoperated and that consequently front contact **TT_{b4}** remains open. Route relay **TK_h** cannot therefore send auxiliary relays **TP_{a/e}**, **TQ_{a/e}**, **TR_{a/e}** the signals concerning the values of **W**, **X** and **Y** through the action of its first three front contacts (**TK_{h1}** . . . **TK_{h3}**).

50 It is the next three front contacts (**TK_{h4}**, **TK_{h5}** and **TK_{h6}**) that are used for this purpose in the case of rerouting. To do so, they are supplied by suitable jumpers from discrimination wire **P_{2c}**, which is grounded by the closing of front contact **TT_{a4}**.

55 It will be assumed that the rerouting of the call characterized by the number 931-25-70 meets the following values for **W**, **X** and **Y**:

$$W=3-X=1-Y=8$$

60 As reference to a table mentioned before will show, these values correspond to the energization of the following code relays:

EW_a, **EW_b**, **EX_a**, **EX_e**, **EY_d**, **EY_e**

65 The control of these relays is provided by auxiliary relays **TP_a**, **TP_b**, **TQ_a**, **TQ_e**, **TR_d**, **TR_e**, which pull up. Only the energizing circuit of relays **TP_a** and **TP_b** will be described herein (it being easy to deduce therefrom those of the other relays): battery, middle winding of relay **TP_b**, upper winding of relay **TP_a**, wire **Wa3** through cable **W**, jumper between terminals **Hw3** and **G84**, front **TK_{h4}**, wire **ch**, terminal **Ech** jumpered to input terminal **I2c**, wire **P2c** through cable **P**, front **TT_{a4}**, **TT_{f3}**, ground.

70 As regards the ground, it will be recalled that it is sent by secondary toll-relay **TN_e**, which (thanks to a

previously-mentioned jumper) is energized in parallel with route relay TK_h . The tolls to be charged to the calling subscriber in the event of rerouting must obviously be the same as where a normal path is used.

It has been pointed out before that rerouting is necessary when no normal path is available from the originating to the terminating office.

Rerouting can also be required of the register where, a certain time after the seizure of an originating connector associated with a normal path, no dialing tone has been received by such originating connector from the terminating connector. This can for example be due to a fault on the transmission line involved or to non-seizure of the terminating connector.

At the end of the lag provided, the originating connector sends a positive to ground polarity over wire Aa_2 , this causing the pulling up of relay EF_a like before: ground, relay EF_a , rectifier EQ_4 , wire Re through cable R , front RE_{p6} , wire Fa_2 , back RE_{q6} , RD_01 , wire Ba_2 through cable B , front CE_{e8} , wire Aa_2 brought to a positive to ground polarity in the originating connector.

The pulling up of relay EF_a then causes in the same manner previously described the release of the relays engaged subsequently to the energization of relay ED_p in the group-selecting operations.

It is to be noted in this case that rerouting is called for even though there may be at that instant free direct lines that will allow putting the call through without rerouting.

The case will now be considered of absent subscribers. Two eventualities can arise. The absent subscriber may be either a called or a calling subscriber. It will be assumed first that he is a called subscriber. To go back to a common example, it will be assumed that the called absent subscriber is served by the same exchange as the calling subscriber and that his number is 828-25-70. The routing of a call to that number has already been described in detail. In the example now under consideration, it is quite obvious that the register can be informed that the called subscriber is absent only at the end of the line-selecting operations. A special polarity (low negative to ground potential) is then sent over discrimination wire F_d from the called subscriber's connector through the line-selection marker, the receiver and receiver connector CT . This low negative polarity sent over wire F_d (Fig. 2) causes the pulling up of discrimination relay RA_o : ground, relay RA_n , relay RA_o , rectifier RQ_1 , wire Bc_1 across Figs. 2, 3 and 5, front EF_{i9} , above-mentioned wire F_d .

Relay RA_n , in series with relay RA_o , is a marginal relay and it stays unoperated.

The pulling up of discrimination relay RA_o tells the register that the called subscriber is an absent subscriber. The energizing circuit of relay EC_m is prepared through the closing of front contact RA_{o2} . The energizing circuit of relay RA_k is completed by the closing of front RA_{o3} .

The pulling up of relay RA_k entails the pulling up of relay EC_m by the closing of front contact RA_{k1} : battery, relay EC_m , wire De through cable D , back RA_{n1} , front RA_{o2} , back RA_{m1} , front RA_{k1} , ground.

The closing of front RA_{k2} completes a holding circuit for RC_{gh} .

Relay EC_m completes a holding circuit for itself through the closing of its front contact EC_{m1} . The opening of back contact EC_{m2} breaks the energizing circuit of relay EF_f , which releases.

The closing of front contact EC_{m3} completes the energizing circuit of relay EF_c , which pulls up: battery, left-hand winding of relay EF_c , front EC_{m3} , EF_{i10} , ground on wire tg .

The closing of front contact EC_{m4} prepares the energizing circuit of translator-seizing relay EJ_q . A ground is applied to absent-subscriber discrimination wire En by the closing of front contact EC_{m5} .

The energization of relay EF_c controls as before the release of the relays that were engaged in controlling the group- and line-selecting operations.

The release of relay EF_f and the energization of relay EJ_q occurring after the release of relay EF_c has the effect of placing the register in a position to call the translator.

The translator is seized in accordance with the usual methods. Since the code 965 is reserved for local calls, no route relay can energize in the translator owing to the reception of this code.

It is known that the release of the relays engaged in controlling the group- and line-selecting operations is characterized by the release of relay EF_c and the energization of relay EF_b . Relay EF_b grounds wire Ei through the closing of its front contact EF_{b4} . Consequently, relay TT_a pulls up upon the seizure of the translator. The energizing circuit of this relay has further been described in connection with the rerouting.

A route relay TK_c has been provided for absent subscribers, be they called or calling subscribers. This relay is energized by the ground applied to absent-subscriber discrimination wire En thanks to a jumper connecting in allotter RT output terminal B_c to the input terminal Ec associated with route relay TK_c .

This relay in effect pulls up upon the seizure of the translator: battery, route relay TK_c , terminal Ec jumpered to terminal B_c , wire En through cable E and translator connector CT , front EC_{m5} , ground.

The pulling up of route relay TK_c will allow sending the register the signals that will enable it to control the transfer of the call to an operator. It will be assumed that the corresponding values of W , X and Y are: $W=3$, $X=5$, $Y=1$.

The toll signal is not included, since it is a question of a call to an operator, not to be charged.

The control of the auxiliary relays providing the sending of the above-mentioned values to the register is effected by front contacts TK_{c4} , TK_{c5} and TK_{c6} , supplied by discrimination wire P_{1c} through a jumper connecting in allotter RT output terminal I_{1c} to input terminal Ecc . It will be noted that discrimination wire P_{1c} is grounded through the closing of front contact TT_{a3} .

When the register controls the group-selecting operations under the control of the translator, it is known that relay ED_p cannot pull up before the translator has sent the register the signals relative to W , X , Y and Z and the corresponding code relays have pulled up. In the special case of ringing the operator, relays $EZ_{a/e}$ stay unoperated. To allow the pulling up of relay ED_p , provision is made to short-circuit the control-contact pyramid associated with relays $EZ_{a/e}$. To do so, use is made of two auxiliary contacts (EY_{a5} and EY_{e5}) of relays EY_a and EY_e , which are connected in series to the output of said contact pyramid. It will be recalled that relays EY_a and EY_e actually correspond to the value $Y=1$.

The operators are reached directly by the group-selecting means the same way as by local circuits, as was already pointed out at the beginning of the present description. Hence the need of making Y equal 1, which leads to the sending of no digit. Owing to this, provision has been made for the short-circuiting of the chain of directing relays by front contacts EY_{a3} and EY_{e3} . Consequently, relays RA_p , EK_c and EL_{jk} pull up upon the energization of relay RE_q , which normally controls the beginning of the operations involved in sending the digits to the outside circuit in the case of an area call.

The energizing circuit of relay EK_c has already been described. The energizing circuit of relays EL_{jk} and EA_p is as follows: battery, left-hand winding of relay EL_{jk} , wire R_m through cable R , upper winding of relay RA_p , wire R_l through cable R , front EY_{a3} , EY_{e3} , wire Ro through cable R , front EK_{o1} , back RD_{d1} , ground on wire D_b .

It is known that the energization of relay RA_p charac-

terizes the end of the operations involved in sending the dialing pulses to the outside circuit in the case of an area call. It will be noted in the present example that this relay pulls up upon the energization of relay REq , thus eliminating the operations relative to the sending of dialing pulses corresponding to the resending of digits. It is known that the energization of relay RAp immediately brings about the release of the register. The calling subscriber is then connected to an operator, who tells him that the called subscriber is an absent subscriber.

Where the calling party is an absent subscriber, relays RAo , RAl and ECm pull up as soon as the register is connected to that subscriber. The energization of relay RAo is this time controlled by the application of a low negative polarity to discrimination wire $Ac1$ from the calling subscriber's connector. The energization of translator-seizing relay EJq is immediate, because front contact $ECm4$ completes the energizing circuit of this relay while the register has not yet received any dialing pulse from the calling subscriber. The seizure of the translator is effected like before. Route relay TKc pulls up over a circuit already described. This route relay does not however bring about the transfer of the calling subscriber to the previously-mentioned operator.

In effect, the translator is informed that the absent subscriber is a called or a calling subscriber by the fact that relay TTa is or is not pulled up. It is known that actually in the case of an absent called subscriber relay TTa pulls up owing to the ground applied to wire Ei by front contact $EFb4$. On the other hand, this relay stays unoperated in the case of an absent calling subscriber, because relay EFb is not energized. Owing to this, translator relay TTb pulls up as in the case of an ordinary subscriber. In short, the sending of a ground over wire En and the pulling up of relays TTa and TTf characterize an absent calling subscriber. To control the group-selecting operations that will allow transferring an absent calling subscriber to a special operator, use is made of the first three front contacts ($TKc1$ . . . $TKc3$) of route relay TKc , supplied by discrimination wire $P1b$. To do so, output terminal $11b$ is jumpered to the input terminal Ebc supplying front contacts $TKc1$ . . . $TKc3$. The values provided in this case for the routing of the call are: $W=3$, $X=4$, $Y=1$.

It will now be assumed that the calling subscriber is a restricted-service subscriber and that he dials a number he is not entitled to call. This fact is characterized in the register by a strong negative to ground polarity applied to wire $Ac1$ from that subscriber's connector. This strong polarity causes the two discrimination relays RAo and RAn to pull up. Relay RAl pulls up over a circuit already described.

The pulling up of relays RAo and RAn entails the pulling up of relay ECn through the grounding of wire Df by the decoding pyramid associated with the discrimination relays. This relay holds through the closing of front contact $ECn2$. A ground is applied to wire Em through the closing of front contact $ECn1$.

If the calling subscriber dials the number of a local call, the pulling up of relay ECn is inoperative.

If the calling subscriber dials the number of an area call to which he is not entitled, the translator is seized as is known and relay TTe pulls up due to the grounding of wire Em . Relay TTf stays unoperated owing to the opening of back contact $TTe1$.

The pulling up of relay TTe causes through the closing of its front contacts $TTe3$ and $TTe4$ the grounding of a certain number of discrimination wires.

In order to fix ideas it will be assumed that the calling party dials the number 828-25-70. It is known that upon the seizure of the translator, such a number causes the pulling up of route relay TKh . This relay cannot send the register the signals required for establishing the wanted connection, since the first three front contacts ($TKh1$ . . . $TKh3$) are not supplied, owing to the falling

back of relay TTf (front contact $TTf3$ open). To transfer the calling subscriber to an operator, provision has been made to use three front contacts ($TKh7$, $TKh8$, $TKh9$) supplied from discrimination wire $P6a$. This wire $P6a$ is grounded due to the pulling up of relay TTe and the closing of front contact $TTe4$. A jumper is provided in allotter RT between the output terminal $I6a$ associated with discrimination wire $P6a$ and the input terminal Edh corresponding to the three front contacts $TKh6$ . . . $TKh9$. The three front contacts furnish the signals to the register in accordance with known methods, the signals being in this case:

$$W=1, X=6, Y=1$$

15 The calling subscriber is then transferred to an operator in accordance with a known method.

The case will now be discussed of a call coming from a toll circuit. The register is seized like in the case of an ordinary subscriber. The fact that the call is from a toll circuit is characterized in the register by the pulling up of discrimination relays RAm and RAl . (Sending of a strong positive polarity over wire $Ac1$.) The pulling up of these relays entails the pulling up of relays RAl and ECp over circuits easy to trace. It will be assumed that the call from such a circuit is intended for a subscriber served by the exchange comprising the register forming the subject of the present discussion. In that case, the register receives from the incoming circuit only four digits, representing the numerical portion of the called subscriber's number. Since the register receives only four digits and these four digits represent the numerical portion of the called number, they must be registered by the registering relays associated with the digits M , C , D and U . To do so, the five wires Ca . . . Ce are immediately directed to registering relays ERa/e . . . EUa/e . For that purpose, the three front contacts $ECp1$ . . . $ECp3$ cause the energization of relays $Elcd$, $EGfg$ and $EGij$:

(1) Battery, resistance $ER10$, front $ECp1$, relay $Elcd$, ground over a circuit already described;

(2) Battery, resistance $ER10$, front $ECp2$, relay $EGfg$, ground over a circuit already described;

(3) Battery, resistance $ER10$, front $ECp3$, relay $EGij$, ground over a circuit already described.

45 The connections between front contacts $ECp1$ . . . $ECp3$ and resistance $ER10$ are shown in dotted lines because they exist only where the register must be connected to an incoming circuit sending only the numerical portion of the called number. The closing of front contact $ECp4$ completes the energizing circuit of relay EFf , which pulls up. The front contact $ECp4$ -relay EFf connection is shown in dotted lines for the same reason mentioned above. The closing of front contact $ECp5$ completes the energizing circuit of relay ECo , which pulls up: battery, relay ECo , front contact $ECp5$, ground on wire Dh .

50 Relay ECp completes a holding circuit for itself through the closing of its front contact $ECp6$: battery, relay ECp , front contact $ECp6$, ground on wire tg . The pulling up of relay EFf characterizes the fact that the register is not to be associated with a translator.

55 Relay ECo completes a holding circuit for itself through the closing of its front contact $ECo2$: battery, relay ECo , front contact $ECo2$, ground on wire tg . The energizing circuit of relay RAq is completed by the closing of front contact $ECo3$: battery, resistance $RR5$, relay RAq , front contact $RCo3$, ground on wire Db .

60 The energization of relay RAq is inoperative. In the present case, therefore, the register behaves as if it had already received the three digits of the code of the local call (965, energization of relay EFf). The following operations involved in the group- and line-selections will develop like before.

65 In the case of a circuit call intended for a satellite

of the connecting office under consideration, the number of digits received exceeds four. It will be assumed that the present register is designed for example to receive 5-digit circuit calls intended for satellites. In that case, front contacts $ECp1$ and $ECp2$ are so connected to resistance $ER10$ that relays $Elcd$ and $EGfg$ pull up upon the energization of relay ECp . Further, a connection is provided between front contact $ECp4$ and wire Ep , relay EFf being this time further controlled by said front contact.

Upon the reception of the first digit, relay EJq pulls up, owing to the closing of front contact $RJ1$, in accordance with a known method. The translator is told that the call is coming from a circuit by the grounding of wire Ej by front contact $ECo1$, the effect of this being to cause the pulling up of relay TTc and to prevent the energization of relay TTf . The pulling up of relay TTc grounds certain discrimination wires.

In the register the closing of front contact $ECp4$ grounds wire Ep , which in the translator terminates at a terminal B_e of allotter RT . This terminal is jumpered to one of terminals $B10/99$, thus making the 5-digit circuit call equal to an area call. It is well to note in fact that the first digit received in the case of a circuit call is registered at the same group of registering relays as the third digit of an ordinary area call. In the case of a call coming from a circuit, therefore, everything happens as if it were a question of an area call, where the first two digits of the called number would not be sent to the translator. In that case, none of terminals $B10/99$ would be grounded. This observation allows understanding why terminal Ep is connected to one of output terminals $B10/99$. Things are thus brought back to the case of an area call and the translation can be had of the first digit received from the circuit, because that digit actually behaves like the third digit in the number of an area call. The translation of the first digit received, which is registered in the translator by the group of relays $TBa \dots TB_e$ and TFa/j , can be had in accordance with a known method from the B terminal chosen from among the 90 terminals $B10/99$. This translation entails the pulling up of the route relay, which thereupon sends the register the information required for the routing of the call.

The supply of the first 3 front contacts of the above-mentioned route relay is provided by one of the discrimination wires grounded owing to the pulling up of relay TTc . The other groups of three front contacts can be used in the case of rerouting, for example.

The call-routing operations develop as already described. It will be noted however that there is no sending of metering pulses, since it is here a question of one circuit calling another. To meet this requirement, an additional contact of relay ECo is used. Contact $ECo4$ is connected in series with contact $Elk1$. Consequently, relay RAp pulls up upon the energization of relay $ELjk$. It is known that relay $ELjk$ directs the control wires of the scanning relays in order to control the sending of metering pulses. Relay RAp controls the release of the register. The fact that the register is released upon the energization of relay $ELjk$ therefore prevents the sending of metering pulses to the outgoing circuit. The release of the register by relay RAp is however delayed, because back contact $RAp4$ is short-circuited by front contact $RAq2$ of relay RAq . This relay RAq is short-circuited by front contact $RAp2$ and accordingly releases with a slight delay. During the moment that relays RAp and RAq are pulled up simultaneously, wire $Bc2$ is grounded to modify the feeding bridges, because in the example here chosen the calling subscriber is a circuit: wire $Bc2$, front $RAp1$, $RAq1$, ground.

When relay RAq releases, the ground is removed from wire $Bc2$ and the short-circuit is removed from back contact $RAp4$, this causing the release of the register.

It may happen that in the case of long-distance toll

calls an intermediate office will receive the full number of the called subscriber. Depending upon the scheme of the telephone system involved, said intermediate office must resend all or part of the number it has received.

5 The register is so told by the application of a low positive polarity to discrimination wire $Ac1$, the effect of this being to cause discrimination relay RAm to pull up over a circuit already described. Marginal relay $RA1$ stays unoperated in that case. Relay RAk then pulls up 10 in accordance with a method already described. Consequently, relay ECo is energized over the following circuit: battery, relay ECo , wire Dh through cable D , back $RA1$, $RAo1$, front $RAm1$, $RAk1$, ground.

The operation of relay ECo has already been described. Due to the register's receiving a full 7-digit number, its operation is approximately the same as if said number had been dialed by an ordinary subscriber. A translator is seized after the reception of the third code-digit.

15 20 The control of the group-selecting and pulse-resending operations is thereupon effected as previously described.

The case will now be considered of a call to special services. It has been arranged that these services should be rung by dialing numbers beginning with the digit 1.

25 It will be assumed by way of example that a subscriber dials the number 14. Upon the reception of digit 1, registering relays EQa and EQe pull up, as well as relay EEm , whose energizing circuit has just been completed 30 as follows: battery, relay EEm , front $EOe3$, $EOa3$, ground over a circuit already described.

The closing of front contact $EEm3$ prepares the energizing circuit of translator-seizing relay EJq .

After the reception of the second digit, relay $EGfg$ pulls up and completes the energizing circuit of relay 35 EJq , which pulls up: battery, relay EJq , back $EFf11$, $EDp4$, $EDq2$, $EEo1$, front $EEm3$, $EGg1$, ground over a circuit already described.

The translator is thus seized upon the reception of the 2nd digit.

40 The reception of digit 1 at the translator causes the grounding of terminal Ba over the following circuit: terminal Ba , front contacts $TEk2$, $TAe3$, $TAa3$, ground.

A special relay (TKa) is provided for the routing of the call. This relay is supplied by terminal Ba over a 45 jumper connecting said terminal Ba to terminal Ea .

This relay, like the other route relays, comprises three groups of three front contacts. Its tenth front contact is used to send the auxiliary relays the signal relative to Y , namely, $Y1$, in the case of a call terminating at an operator's position. Thus, regardless of the special service called, the route relay automatically furnishes the special signal $Y=1$. The first contacts of each of the three-contact groups, namely, contacts $TKa1$, $TKa4$, $TKa7$, are intended to control the auxiliary relays TPa/e sending the signals concerning the value of W . The second front contacts ($TKa2$, $TKa5$, $TKa8$) control the auxiliary route-relays over their front contacts and in response to the second digit received of the called number furnish the signals relative to the value of X .

60 The third contacts ($TKa3$, $TKa6$, $TKa9$) are not used.

In the case of a call to number 14 for example by an ordinary subscriber, use is made of front contacts $TKa4$ and $TKa5$, supplied from discrimination wire $P5a$, which 65 is grounded due to the closing of contact $TTf5$. To do so, a jumper is provided in allotter RT connecting the output terminal $I5a$ associated with discrimination wire $P5a$ to the input terminal Eca supplying front contacts $TKa4 \dots TKa6$.

The pulling up of this route relay immediately furnishes the translator the following elements: $W=1$, $Y=1$.

These elements are furnished by front contacts $TKa4$ and $TKa10$.

An auxiliary route-relay TNa controlled by front contact $TKa5$ is provided. To do so, the output terminal 75

G5 associated with front contact $TKa5$ is jumpered to the input terminal Na associated with relay TNa .

Front contacts $TNa1/10$ are connected to the ten outgoing wires $Ka1/10$ of second-digit decoding pyramid D2C and to the ten output terminals $Ga1/10$. These terminals are designed to control the auxiliary code-sending relays relative to the digit X in the group selection. In the example chosen it will be assumed that the value of X for the special service having the number 14 is: $X=4$.

A jumper is provided in allotter RT between terminals $Ga4$ and $Hx4$, its effect being to cause the pulling up of auxiliary relays TQe and TQc : battery, middle winding of relay TQe , lower winding of relay TQc , wire $Xa4$ through cable X, terminal $Hx4$ connected to terminal $Ga4$, front $TNa4$, wire $Ka4$ grounded by second-digit decoding contact pyramid D2C.

The register having received the information required for the group selection, it controls the establishment of the connection.

It will now be assumed that a subscriber dials a non-existent number. It will be assumed that 931-75-70 is such a number.

It is known that the reception of the code 931 by the translator requires knowing the fourth digit of the number. When the register calls the translator in a second time, after the reception of the fourth digit (the digit 7 in the example chosen), route relay TKh and metering relay TNe pull up. To characterize the fact that 9317 corresponds to a non-existent number, terminal Ie of allotter RT is grounded. This is done by jumpering the output terminal $Fe7$ associated with front contact $TNe7$ to terminal Ie . The grounding of this terminal has the effect of causing the pulling up of relay ELq (Fig. 6): battery, left-hand winding of relay ELq , wire Eq through cable E and translator connector CT, terminal Ie grounded.

The switching into operating position of directing contact $ELq1$ removes the ground from code-sending wires Eaa/e , Eba/e , Eca/e , Eea/e and transfers it to wire Ef . The closing of front contact $ELq2$ completes the energization circuit of relay EFc , which pulls up: battery, left-hand winding of relay EFc , wire ha across Figs. 6 and 7, front $ELq2$, ground on wire Eq .

Relay ELq completes a holding circuit for itself through the closing of its front contact $ELq3$: battery, right-hand winding of relay ELq , front $ELq3$, ground on wire tg .

The removal of the ground from the above-mentioned wires Eaa/e . . . entails the release of the digit-receiving relays of the translator and hence the release of the two route and metering relays previously pulled up. The pulling up of relay EFc will cause in accordance with a known method the cancellation of the group selection that was brought about by the pulling up of route relay TKh (it will be recalled that auxiliary relay TNe controls only the tolls).

The grounding of wire Ef by front $ELq1$ tells the translator that the number dialed by the subscriber leads to a non-existent combination. This wire Ef terminates at a terminal Bd in allotter RT. To transfer the calling subscriber to an operator, a special route-relay (TKd) is controlled from terminal Bd . For this purpose, a jumper connects output terminal Bd to input terminal Ed in allotter RT. Consequently, route relay TKd pulls up upon the grounding of wire Ef . The first three front contacts ($TKd1$ . . . $TKd3$) of route relay TKd are used to send the register information that will enable it to control the group-selecting operations that are to connect the calling subscriber to an operator. The first three front contacts of route relay TKd are supplied from discriminating wire $P1a$ by means of a jumper provided between output terminal $I1a$ and input terminal Ebd .

This route relay furnishes the register the following information:

The group selection is thereupon effected in accordance with a known method.

5 The case of a national call will now be described. It is known that in order to make such a call the calling subscriber dials a special number, which will be assumed to be the number 16 by way of example.

Immediately thereafter, following the reception of a special tone, the subscriber dials an 8-digit number.

10 When a subscriber dials the number 16, relay EEm pulls up in accordance with a known method (this pulling up is caused because the first digit dialed is the digit 1). Relay EEn pulls up following the reception of digit 6: battery, relay EEn , front $EEm2$, $EPc5$, $EPb5$, $EGg3$, $EEm1$, $EOe3$, $EOa3$, ground over a circuit already described.

15 Relay EEn completes a holding circuit for itself by closing its front contact $EEn1$: battery, relay EEn , front $EEn1$, ground on wire tg .

20 The switching into operating position of make-break contact $EEn2$ prepares the energizing circuit of translator relay TDk . Contact $EEn3$ prepares the dialing-tone sending circuit (second sending of dialing tone). The closing of front contact EEn short-circuits back contact $EHe2$ in order to allow the registering of eight digits. The opening of back contact $EEn5$ prepares the release of relay EEm . The opening of back contact $EEn6$ breaks the holding circuit of relays EId and $EGfg$, as well as the holding circuit of registering relays EOa , EOe , EPb , EPc , which are pulled up owing to the reception of the number 16.

25 The release of these relays entails the release of relay EEm .

30 The closing of back contact $EId4$ completes again the dialing-tone sending circuit to the calling subscriber's loop. This circuit, which is already known, will not be described. In the present case, the registering relays are unoperated and the calling subscriber can dial the 8-digit number of the called subscriber. The registering of that number is done like before. Upon the reception of the first digit, relay EHh pulls up as is known and through the closing of its front contact $EHh3$ completes the energizing circuit of relay EEo , which pulls up in turn: battery, relay EEo , front $EHh3$, $EEn1$, ground on wire tg .

35 The pulling up of relay EEo prepares the energizing circuit of translator-seizing relay EJq through the closing of its front contact $EEo1$. Front contact $EEo2$ completes a holding circuit for relay EEo . The holding circuit of relays EId and $EGfg$ is prepared by the closing of front contact $EEo3$. The energizing circuit of relay RCf is prepared by the closing of front contact $EEo4$. The opening of back contact $EEo6$ will allow directing the control wires of the scanning relays to front contacts $EVa2/e2$.

40 45 After the reception of the number's second digit, relay $EGfg$ pulls up and completes the energizing circuit of relay EJq : battery, relay EJq , back $EFf11$, $EDp4$, $EDq2$, front $EEo1$, $EGg4$, ground over a circuit already described.

50 55 The translator is seized in accordance with the usual methods. Upon such seizure, relay TDk pulls up, thus telling the translator that the call to be put through is a national call: battery, relay TDk , wire Ek through cable E and translator connector CT, front $EEn2$, ground.

60 For a national call, the subscriber number can begin with the digit 1. Consequently, the quantity of combinations obtainable with the number's first two digits is 100.

65 70 Ten relays TDa/j have been provided performing a function identical with that of the nine relays TEb/j discussed with reference to area calls. These relays are supplied through front contacts $TDk2/11$ by the ten outgoing wires $Ja1$ . . . $Ja10$ coming from the first-digit decoding contact pyramid.

These ten relays each have ten front contacts or a total of 100 front contacts, referenced $TDa/j/2/11$. Each outgoing wire of second-digit decoding contact pyramid D2C is multiplied to 10 front contacts of a predetermined rank of relays TDa/j . Thus, wire $Ka1$ is multiplied to front contacts $TDa2$, $TDa3$ . . . $TDa10$. One hundred outgoing wires are thus obtained, terminating at 100 output terminals (referenced $Aoo/99$) of all other RT.

The control of the route relays is identical with that previously described with reference to area calls.

As regards the register, it is well to explain that relay EEm does not pull up if the calling subscriber's number begins with the digit 1. In fact, owing to the pulling up of relay EEn , back contact $EEn5$ is open. Similarly, 15 relay EFf cannot be energized where the calling subscriber dials a number beginning with 965.

The chain of registering relays comprises five additional relays (EVa/e) intended to register the number's eighth digit. It often happens that during the registering of the digits of a number for an area call the holding circuit of the counting relays of counter NR is broken upon the energization of relay $EHde$ through the opening of back contact $EHe2$, that is, after the registering of the number's seventh digit.

In the present case, contact $EHe2$ is inoperative, being short-circuited by $EHe2$ and the two contacts in series $EEn4$ and $EHg2$. It is only after the reception of the eighth digit of a number for a national call that relay EHg pulls up and opens the holding circuit of the counting relays of counter NR.

As regards the sending of numerical pulses to the outgoing circuit, it will be noted however that, owing to the opening of back contact $ECo4$, relay $ELjk$ does not pull up at the same instant as relay $ELgh$, thus allowing the sending of the pulse trains corresponding to the number's eighth digit.

It may happen that, because of the geographical location of the system, traffic outgoing from one exchange to some other exchange is heavy as compared with traffic outgoing to all the other terminating exchanges to which such originating exchange has access. These considerations further in no way affect the local traffic of the particular exchange involved, which, for readily understandable reasons, generally far exceeds the outgoing traffic. The numbers for calls to the above-mentioned distant exchange obviously begin with the most diverse digits, comprised between 2 and 0 (the digit 1 being reserved for special services). If all the numbers beginning with a given first digit are considered, it is possible to group them into 3 categories in accordance with the destination:

(1) A category of numbers involving only calls intended for the distant exchange with which the traffic is the heaviest;

(2) A category of numbers giving access to any distant exchange;

(3) A category of numbers not giving access to the distant exchange with which the traffic is the heaviest.

From the foregoing it can be seen that upon the reception of the first digit of a number comprised in the first category mentioned above it is possible to determine the route signals relative to such a call without the aid of a translator. On the other hand, the determination of the tolls requires the seizure of a translator after the register has received the code of the number of the wanted connection. It follows from this that, if the information required for determining the proper route is determined in the register upon the reception of the first digit of the called number, considerable time is saved in the routing of the call involved.

It will be assumed for example that all calls whose number begins with the digit 2 meet that requirement. The register comprises a relay (EFg) whose winding is

connected to the output of the first-digit decoding contact pyramid.

Upon the reception of the first digit (digit 2 in the example chosen) relay EFg pulls up: battery, relay EFg , front $EOe4$, $EOb3$, ground over a circuit already described.

Over its front contacts $EFg1$ . . . $EFg6$, relay EFg completes energizing circuits for six of the code relays EWa/e , EXa/e , EYa/e . Front contacts $EFg1/2$, $EFg3/4$, $EFg5/6$ are connected to wires Ewa/e , Exa/e , Eya/e by connections shown in dotted lines because they can be modified in accordance with operating requirements. Front contact $EFg7$ controls the starting of the timing device. Front contact $EFg8$ short-circuits front contact $EDp2$ and thereby causes the pulling up of the relay $EFjk$ starting the group-selecting operations. A ground is applied to wire Iu towards fault register ED by the closing of front contact $EFg9$.

The translator is seized following the reception of the number's third digit. A tolls relay pulls up and sends the tolls to the register. The connection is thereupon established like before.

It may happen that the calling subscriber dials a non-existent number. Upon the reception of the number's first digit, the register controls the seizure of a translator like described before. Upon its seizure, after reception of the number's third digit, the translator causes the pulling up of relay ELq (Fig. 6) in accordance with a method already described. This relay cancels, like previously described, the selections already made and further, through the opening of its back contact $ELq4$, causes the release of relay EFg . Things are thus back to the case previously described.

It has already been shown several times that the building-up time of the group-selecting, line-selecting and other operations is controlled by a timing device. If the building-up time of any of these operations is abnormal, time relay $RDhi$ pulls up. Through its front contact $RDi1$, it completes the energizing circuit of relay RDk , which pulls up: battery, relay RDk , front $RDi1$, back $RDj5$, ground on wire D_b .

The closing of front contacts $RDk1$ . . . $RDk3$ brings the register into calling position, for the purpose of connecting it to a fault register. Front contact $RDk4$ holds relay RAd and hence the register in case the calling subscriber should hang up.

Fault register ED for example is connected by means not shown to the register forming the subject of the present description. It is told of the nature of the fault appearing in the main register by testing the polarity applied to wires Id . . . Ix . This testing allows in fact determining the moment at which the fault involved occurred. For example, if the group-selecting operations are slow in being performed, relay EFe does not pull up hence relay $EFjk$ remains unoperated. When the fault register is seized, the fact that it verifies the grounding of wire Is tells the fault register that relay $EFjk$ is still pulled up and that the fault occurred in the group-selecting operations.

It may happen that the scanning relays will operate improperly and that the number of these relays pulled up during the sending of the pulse train for a given digit will be other than two. In that case, the control-contact pyramid of these relays causes the energization of relay RDl , which pulls up.

Over its front contact $RDl1$, relay RDl completes the energizing circuit of relay RDk , which pulls up: battery, relay RDk , back $EFb3$, front $RDl1$, back $RDj5$, ground on wire D_b .

The closing of front contact $RDl2$ completes the energizing circuit of relay RDo , which pulls up: battery, relay RDo , front $RDl2$, $RAd4$, back $RCf5$, $EFc2$, ground.

Relay RDl completes a holding circuit for itself through the closing of its front contact $RDl3$; battery, relay RDl , front $RDl3$, back $RDh1$, ground on wire D_b .

Relay RDo opens the loop towards the originating connector at RDo1. Front contact RDo2 short-circuits back contact RCf1, this preventing the premature release of the register. The energizing circuit of relay RCf is completed by the closing of front contact RDo3; battery, relay RCf, front RDo3, ground on wire Db.

The opening of contact RCf1 prepares the release of the register. A ground is applied to wire In towards fault register ED by the closing of front contact RCf2. The timing device is started by the closing of front contact RCf3. Relay RCf completes a holding circuit for itself over wire tg by the closing of its front contact RCf4. The ground is broken on test wire Bf2 by the opening of back contact RCf5.

If the originating connector releases before relay RDhi pulls up, relay RDo falls back and releases the register through the opening of its front contact RDo2. Otherwise, relay RDhi pulls up and causes the seizure of a fault register in accordance with a known method.

To complete this description, the case will be considered where a calling subscriber fails to dial any number after having removed his handset or else dials an incomplete number.

It is known that upon removing his handset the subscriber is connected to the register and that relay RCe remains unoperated so long as the subscriber fails to dial. Likewise, at the end of each dialing-pulse train, relay RCe falls back until the reception of the next train.

When this relay is in unoperated position, it prepares over its front contact RCe3 the holding circuit of relay RCi. Cam RK1 sends a ground periodically over wire k1. If relay RCe is in unoperated position when wire k1 is grounded, relay RCi pulls up and holds through the closing of its front contact RCi1, which completes the following holding circuit for it: battery, right-hand winding of relay RCi, front RCi1, back RCe3, wire Da through cable D, back EH2, ground on wire tg.

At RCi2, relay RCi prepares the energizing circuit of relay RCj. If at the end of a certain period of time the subscriber has not dialed or has stopped dialing, relay RCi is still pulled up at the instant when a second cam (RK2) sends a ground over wire k2, the effect of this being to cause relay RCj to pull up; battery, upper winding of relay RCj, front RCi2, wire k2, cam RK2, ground.

Relay RCj completes a holding circuit for itself through the closing of its front contact RCj1; battery, lower winding of relay RCj, front RCj1, RAc1, ground.

Relay RCj grounds wire Eo via its front contact RCj4. Translator-seizing relay EJq is energized by the closing of front contact RCj5; battery, relay EJq, back EF11, EDp4, EDq2, EEo1, EEm3, front RCj5, ground over a circuit already described.

The translator is seized in accordance with known methods. Terminal Bb of allotter RT is grounded due to the closing of front contact RCj4. A route relay (TKb) is provided to transfer a faulty subscriber to an operator. To do so, a jumper is provided in allotter RT between output terminal Bb and input terminal Eb.

The first three front contacts (TKb1 . . . TKb3) of route relay TKb are used to send the register signals that will bring about the transfer of a faulty subscriber to an operator. It will be assumed that these signals are as follows: W=3, X=6, Y=1.

The three contacts TKb1 . . . TKb3 of relay TKb are supplied from discrimination wire P1a through a jumper provided in allotter RT between the output terminal 11a associated with discrimination wire P1a and the input terminal Ebb supplying the three front contacts TKb1 . . . TKb3.

The transfer of a faulty subscriber to an operator is achieved in accordance with a known method.

It is quite obvious that the foregoing descriptions have been given only as non-limitative examples and that numerous modifications can be made without departing from the scope of the invention.

Thus, for example, the devices registering the numbers dialed or the digits translated could be made up of vacuum tubes or rotary switches.

5 The relay chains described can be replaced with other chains of different design but performing the same functions.

The numbering scheme used is given only as an example and can be changed at will in accordance with operating requirements.

10 The codes used for the fast sending of information between the various equipments can obviously be different from those used in the course of the present description.

15 While I have described above the principles of my invention in connection with specific apparatus, it is to be clearly understood that this description is made only by way of example and not as a limitation to the scope of my invention as set forth in the objects thereof and in the accompanying claims.

What is claimed is:

20 1. A telephone system comprising a local exchange, a plurality of lines in said exchange, a plurality of trunks leading to other exchanges, a plurality of registers, means for seizing a register and connecting it to a line in response to a call originating on that line, means in said

25 register for registering a predetermined number of digits, a plurality of translators, means in said register responsive to the registration of said predetermined number of digits for seizing one of said translators and for transmitting said registered digits to said translator, means

30 in said translator responsive to the digits transmitted thereto from said register and, operable if said transmitted digits are sufficient for the determination of the routing of the call for producing the selective combinations required for completing the connection of the calling line

35 to a trunk and operable if supplementary digits are necessary for such determination for transmitting a signal back to said register, means in said register responsive to said signal for releasing said translator, means in said register responsive to the registration of said necessary supplementary digits for again seizing one of said translators

40 and transmitting said predetermined digits and said supplementary digits thereto, a plurality of partial number circuits adapted to receive calls from other exchanges, means in each partial number circuit responsive to an incoming call for seizing a register and transmitting a special signal to said register, means in each register responsive to said special signal for disconnecting the registering means corresponding to the digits not included

45 in a partial number, whereby the transmitted digits are registered in the registering means corresponding to said digits and said register will control the routing and ringing operations without requiring the intervention of a translator.

50 2. A telephone system, as defined in claim 1, further comprising a plurality of complete number circuits adapted to receive incoming calls, means in each complete number circuit responsive to a call therein for seizing a register and transmitting a special signal thereto characterizing the nature of the circuit, and means in each register responsive to said special signal, for preparing it for the reception and registration of a predetermined number of digits.

55 3. A telephone system, as defined in claim 1, in which each register is adapted to receive a toll-access signal, further comprising means in each register responsive to the receipt of a toll-access signal for releasing the registering means used for registering the toll-access signal and preparing said means for receiving the complete signal for characterizing the called subscriber within the

60 national network, means in each register, in response to the receipt of a predetermined number of digits, for thereupon seizing a translator and transmitting to it a special signal, means in each translator, responsive to said special signal for preparing said translator to control

65 the translations required for the routing of national calls,

70

75

the translations required for the routing of national calls,

whereby the same translators may be used for national and regional calls.

4. A telephone system, as defined in claim 1, in which the digits of a special service call include a first digit common to all special service calls and a second digit denoting the category of the calling subscriber, and in which each translator comprises two routing relays, one for translating said first digit and the other for translating said second digit, said translator further comprising means controlled by said relays for transmitting the two translated digits to said register, whereby the call may be routed in a direction determined by the category of the calling subscriber.

5. A telephone system, as defined in claim 1, in which lines assigned to absentee subscribers are provided with means adapted to transmit a signal to the associated register when a connection to such line is completed, further comprising an operator's circuit, means in each register responsive to said signal for causing the release of the connection to said line, the seizure of a translator and the transmission of said signal thereto, means in each seized translator responsive to said signal for transmitting another signal to said register, and means in each register responsive to said other signal for causing the calling line to be connected to said operator's circuit.

6. A telephone system, as defined in claim 5, in which each line assigned to an absentee subscriber is provided with means, responsive to a call originating on said line, for transmitting the first mentioned signal to a seized register, whereby said register will seize a translator and said translator will cause said register to connect the calling line to the operator's circuit regardless of the number dialled.

7. A telephone system, as defined in claim 1, further comprising means in each register responsive to the receipt of the first digit of a number corresponding to a given direction for controlling the routing of the call to a trunk leading to another exchange, means for subsequently comparing the seized trunk with that corresponding to the selective combinations produced by a seized translator after the receipt of the necessary digits, and means operated by said comparing means for releasing the partial connection to said first seized trunk if it is not the same as the trunk selected by said translator.

8. A telephone system comprising an exchange, a plurality of partial number circuits adapted to receive calls from other exchanges, a plurality of registers, means in each partial number circuit responsive to an incoming call for seizing a register and transmitting a special signal to said register, means in each register responsive to said special signal for disconnecting the registering means corresponding to the digits not included in a partial number, whereby the transmitted digits are registered in the registering means corresponding to said digits and said register will control the routing and ringing operations without requiring the intervention of a translator.

9. A telephone system, as defined in claim 8, further comprising a plurality of complete number circuits in the exchange adapted to receive incoming calls, means in each complete number circuit responsive to a call therein for seizing a register and transmitting a special signal thereto characterizing the nature of said circuit, and means in each register, responsive to said special signal, for preparing said register for the reception and registration of a predetermined number of digits.

10. A telephone system comprising a national network including an exchange, a plurality of lines in said exchange, a plurality of registers each register adapted to receive a toll-access signal from a calling line, a plurality of translators, means in each register responsive to the receipt of a toll-access signal for releasing the registering means used for registering the toll-access signal and preparing said means for receiving the complete signal

for characterizing the called subscriber within said national network, means in each register, in response to the receipt of a predetermined number of digits, for thereupon seizing a translator and transmitting to it a special signal, means in each translator responsive to said special signal for preparing said translator to control the translations required for the routing of national calls, whereby the same translators may be used for national and regional calls.

10. 11. A telephone system comprising an exchange adapted to handle special service calls, the digits of a special service call including a first digit, common to all special service calls, and a second digit denoting the category of the calling line, a plurality of lines, a plurality of registers, a plurality of translators, each translator comprising two routing relays, one for translating said first digit, common to all said special services, and the other for translating said second digit, denoting the category of the calling line, means controlled by said relays for transmitting the two translated digits to said register, whereby the call may be routed in a direction determined by the category of the calling line.

12. A telephone system comprising an exchange, a plurality of lines in said exchange some of which may be assigned to absentee subscribers, a plurality of registers, a plurality of translators, an operator's circuit, means connected to each absentee subscriber line for transmitting a signal to the associated register when a connection to such line is completed, means in each register responsive to said signal for causing the release of the connection to said line, the seizure of a translator, and the transmission of said signal thereto, means in each seized translator responsive to said signal for transmitting another signal to said register, and means in each register responsive to said other signal for causing the calling line to be connected to said operator's circuit.

13. A telephone system, as defined in claim 12, in which each line assigned to an absentee subscriber comprises means, responsive to a call originating on said line, for transmitting the first mentioned signal to a seized register, whereby said register will seize a translator and said translator will cause said register to connect the calling line to the operator's circuit regardless of the number dialled.

14. A telephone system comprising an exchange, a plurality of lines in said exchange, a plurality of trunks, a plurality of registers, a plurality of translators, means in each register responsive to the receipt of a first digit of a number corresponding to a given direction for controlling the routing of the call to a trunk corresponding to said direction, means in each register, responsive to the receipt of a predetermined number of digits, for seizing a translator and transmitting said digits to said translator, means in said translator, responsive to the digits transmitted thereto from said register and operable if said transmitted digits are sufficient for the determination of the routing of the call for producing the selective combinations required for completing the connection of the calling line to a trunk corresponding to the direction represented by the received digits, means for subsequently comparing the seized trunk with that corresponding to the selective combinations produced by said translator, and means operated by said comparing means for releasing the partial connection to said first seized trunk if it is not the same as the trunk selected by said translator.
